BED SHEET RETENTION SYSTEMS, SYSTEM COMPONENTS, AND METHODS OF MAKING AND USING THE SAME

This application is being filed as a continuation patent application of, and claims the benefit of priority to, U.S. patent application Ser. No. 19/072,092 filed on Mar. 6, 2025 entitled "BED SHEET RETENTION SYSTEMS, SYSTEM COMPONENTS, AND METHODS OF MAKING AND USING THE SAME," which is a continuation-in-part patent application that claims the benefit of priority to U.S. patent application Ser. No. 18/986,848 filed on Dec. 19, 2024 and entitled "BED SHEET RETENTION SYSTEMS, SYSTEM COMPONENTS, AND METHODS OF MAKING AND USING THE SAME," which is a continuation patent application of, and claims the benefit of priority to, U.S. patent application Ser. No. 18/945,224 filed on Nov. 12, 2024 and entitled "BED SHEET RETENTION SYSTEMS, SYSTEM COMPONENTS, AND METHODS OF MAKING AND USING THE SAME," which is a continuation-in-part patent application that claims the benefit of priority to PCT International Patent Application No. PCT/US2023/079473 filed on Nov. 13, 2023 and entitled "BED SHEET RETENTION SYSTEMS AND METHODS OF MAKING AND USING THE SAME," which claims the benefit of priority to U.S. Provisional Patent Application Ser. No. 63/426,859 filed on Nov. 21, 2022 and entitled "BED SHEET RETENTION SYSTEMS AND METHODS OF MAKING AND USING THE SAME," the subject matter of both of which is hereby incorporated by reference in its entirety.

FIELD OF THE INVENTION

The present invention relates to bed sheet retention devices, and accessories that can be used with bed sheet retention devices, methods of making bed sheet retention devices, and accessories that can be used with bed sheet retention devices, and methods of using bed sheet retention devices, and accessories that can be used with bed sheet retention devices.

BACKGROUND OF THE INVENTION

Known sheet tensioning systems on the market rely on lifting the mattress and working underneath the corners on adjustments and holding the corners of the sheets down. There are elastic bands and such which are marketed to hold the sheets down, but tight bed sheets will come undone unless locked into place. Drawstring tension systems are present in the market, corner elastic suspender type tensioners are also available. Each of these are tedious on installations and settings, each requiring an adjustment depending on what size sheet and mattress you are working with.

Working with these sheet retention systems does not make bed making easier. In fact, such sheet retention systems make it more labor intensive. Such bed aids should not make fighting with bed sheets more difficult, and more of a frustration than the sheet coming off itself. Such a device should feel natural to use, as if it's not even there. It should be a part of the typical bed making process, and helpful in its design.

There is a need in the art for continued improvements in the art of bed sheet retention systems.

SUMMARY OF THE INVENTION

The present invention is directed to bed sheet retention devices, attachable accessories that can be used with and

connected to bed sheet retention devices, and systems that prevent bed sheets from slipping off of a bed, such as in the corners of a bed mattress and/or along a side edge of the bed.

The present invention is directed to bed sheet retention devices and systems. The bed sheet retention devices comprise: one or more sheet-engaging channels positioned along one or more side surfaces of a mattress, each sheet-engaging channel comprising a sheet-locking member comprising (i) an upper sheet-locking channel member, and (ii) a lower sheet-locking channel member positioned below and spaced from the upper sheet-locking channel member, wherein each of the upper sheet-locking channel member and the lower sheet-locking channel member (a) are designed to engage with one or more sheet-locking strips inserted within the sheet-locking member and between the upper sheet-locking channel member and the lower sheet-locking channel member and (b) together provide a channel track profile that extends along a given sheet-locking member. In some embodiments, each sheet-engaging channel of the one or more sheet-engaging channels comprises (1) an upper channel side wall extending away from (i.e., not towards) the mattress, and forms a portion of the upper sheet-locking channel member, (2) a lower channel side wall extending away from the mattress, and forms a portion of the lower sheet-locking channel member, (3) an upper strip engaging member extending downward from the upper channel side wall and towards the lower sheet-locking channel member, and (4) a lower strip engaging member extending upward from the lower channel side wall and towards the upper sheet-locking channel member. The one or more sheet-engaging channels are either (a) an integral component of mattress, and form at least a portion of the one or more side surfaces of mattress, or (b) separate from and combinable with mattress so as to cover at least a portion of the one or more side surfaces of mattress. In these embodiments, the bed sheet retention devices may further comprise one or more sheet locking strips, with each sheet locking strip being sized and designed to be inserted within the sheet-locking member and between (i) the upper sheet-locking channel member and (ii) the lower sheet-locking channel member.

In some embodiments, the bed sheet retention device comprises: a bracket comprising: (a) a horizontally-extending bracket component sized and designed to extend between a bottom surface of a mattress and a support surface under the bottom surface; and (b) one or more sheet-engaging channels connected to said horizontally-extending bracket component, wherein each sheet-engaging channel (1) comprises a sheet-locking member extending along an outer surface of the bracket, and (2) extends substantially within a plane P parallel with said horizontally-extending bracket component or at an angle A to the plane P parallel with said horizontally-extending bracket component, wherein the sheet-locking member comprises (i) an upper sheet-locking channel member, and (ii) a lower sheet-locking channel member positioned below and spaced from said upper sheet-locking channel member, wherein each of said upper sheet-locking channel member and said lower sheet-locking channel member are designed to engage with one or more sheet locking strips and/or one or more of the herein-described attachable accessories.

In some embodiments, the bed sheet retention device of the present invention comprises a bed sheet retention device comprising: (I) a corner bracket comprising: (a) a horizontally-extending bracket component sized and designed to extend between a bottom surface of a mattress and a support surface under the bottom surface; and (b) two or more sheet-engaging channels connected to said horizontally-

extending bracket component, said two or more sheet-engaging channels (1) being separated from one another by a corner of the corner bracket, and (2) extending substantially within a plane P parallel with said horizontally-extending bracket component or at an angle A to the plane P parallel with said horizontally-extending bracket component.

In some embodiments, the bed sheet retention device of the present invention comprises a bed sheet retention device comprising: (I) a corner bracket comprising: (a) a horizontally-extending bracket component sized and designed to extend between a bottom surface of a mattress and a support surface under the bottom surface; (b) one or more sheet-engaging channels connected to said horizontally-extending bracket component, wherein each sheet-engaging channel (1) comprises (a) two sheet-locking members, and (b) an open guided section extending around a corner of the corner bracket, and (2) extends substantially within a plane P parallel with said horizontally-extending bracket component or at an angle A to the plane P parallel with said horizontally-extending bracket component.

In some embodiments, the bed sheet retention devices of the present invention comprise: (I) a side bracket comprising: (a) a horizontally-extending bracket component sized and designed to extend between a bottom surface of a mattress and a support surface under the bottom surface; and (b) one or more sheet-engaging channels connected to said horizontally-extending bracket component, wherein each sheet-engaging channel (1) comprises a sheet-locking member extending along an outer surface of the side bracket, and (2) extends substantially within a plane P parallel with said horizontally-extending bracket component or at an angle A to the plane P parallel with said horizontally-extending bracket component.

In some embodiments, the bed sheet retention device comprises a mattress covering component designed and sized to extend over one or more side surfaces of a mattress, wherein the mattress covering component comprises: (A) one or more side sheet portions that extend over one or more side surfaces of a mattress; and (B) one or more sheet-engaging channels extending along the one or more side sheet portions, wherein each sheet-engaging channel comprises a sheet-locking member comprising: (i) an upper (or first) sheet-locking channel member, and (ii) a lower (or second) sheet-locking channel member spaced from the upper sheet-locking channel member, wherein the upper sheet-locking channel member and the lower sheet-locking channel member (a) are designed to engage with one or more sheet-locking strips inserted within the sheet-locking member and between the upper sheet-locking channel member and the lower sheet-locking channel member, and (b) together provide a channel track profile that extends along a given sheet-locking member. In some embodiments, the mattress covering component is an integral component of mattress, and forms at least a portion of the one or more side surfaces of mattress. In other embodiments, the mattress covering component is separate from and combinable with a mattress so as to cover at least a portion of the one or more side surfaces of mattress (e.g., a removable mattress cover).

The present invention is further directed to attachable accessories that can be used with and connected to bed sheet retention devices. The attachable accessories can be used to provide one or more bed sheet retention system features including, but not limited to, a shelf for placement of keys, phone, or any other object; a cup holder; a basket; a pouch; an electric cord holder; an electric fan support; a charging pad; a light support; an open net support; a closed net

support; a jointed arm device that has a distal arm end that is movable and is designed to hold an object, e.g., a book, a phone, a computer pad, etc., a guardrail extending along a side edge of a bed, or any combination thereof.

5 The attachable accessories of the present invention are suitable for use with bed sheet retention devices, such as the bed sheet retention devices disclosed in International Patent Application No. PCT/US2023/079473, as well as the herein-described bed sheet retention devices. A given accessory 10 may comprise: (a) at least one accessory connecting member, and (b) an accessory body connected to and extending from the at least one accessory connecting member, wherein the at least one accessory connecting member is configured to extend within and connect to one or more corner brackets 15 and/or one or more side brackets of a bed sheet retention device.

The present invention is even further directed to bed sheet retention systems. In some embodiments, the bed sheet retention systems comprises: (I) a bracket comprising: (a) a horizontally-extending bracket component sized and designed to extend between a bottom surface of a mattress and a support surface under the bottom surface; and (b) one or more sheet-engaging channels connected to said horizontally-extending bracket component, wherein each sheet-engaging channel (1) comprises a sheet-locking member extending along an outer surface of the bracket, and (2) extends substantially within a plane P parallel with said horizontally-extending bracket component or at an angle A to the plane P parallel with said horizontally-extending bracket component, wherein the sheet-locking member comprises (i) an upper sheet-locking channel member, and a lower sheet-locking channel member positioned below and spaced from said upper sheet-locking channel member, wherein each of said upper sheet-locking channel member 20 and said lower sheet-locking channel member are designed to engage with one or more sheet locking strips and/or one or more of the herein-described attachable accessories; and (II) one or more sheet locking strips, each sheet locking strip being sized and designed to engage with said upper sheet-locking channel member and said lower sheet-locking channel member of each of said one or more sheet-engaging channels of said bracket.

In some embodiments, the bed sheet retention systems comprise: (I) a bracket comprising: (a) a horizontally-extending bracket component sized and designed to extend between a bottom surface of a mattress and a support surface under the bottom surface; and (b) one or more sheet-engaging channels connected to said horizontally-extending bracket component, wherein each sheet-engaging channel (1) comprises a sheet-locking member extending along an outer surface of the bracket, and (2) extends substantially within a plane P parallel with said horizontally-extending bracket component or at an angle A to the plane P parallel with said horizontally-extending bracket component, 30 wherein the sheet-locking member comprises (i) an upper sheet-locking channel member, and a lower sheet-locking channel member positioned below and spaced from said upper sheet-locking channel member, wherein each of said upper sheet-locking channel member and said lower sheet-locking channel member are designed to engage with one or more sheet locking strips and/or one or more of the herein-described attachable accessories; and (II) one or more of the herein-described attachable accessories, each accessory being sized and designed to engage with said upper sheet-locking channel member and said lower sheet-locking channel member of each of said one or more sheet-engaging channels of said bracket.

In some embodiments, the bed sheet retention systems of the present invention comprises (I) one or more bed sheet retention devices, wherein one or more of the bed sheet retention devices comprises: a corner bracket comprising: (a) a horizontally-extending bracket component sized and designed to extend between a bottom surface of a mattress and a support surface under the bottom surface; and (b) one or more sheet-engaging channels (1) connected to said horizontally-extending bracket component, and (2) extending substantially within a plane P parallel with said horizontally-extending bracket component, and (II) one or more sheet locking strips that engage with one or both of the one or more sheet-engaging channels. As discussed below, the bed sheet retention systems of the present invention may comprise four or more bed sheet retention devices, and four or more sheet locking strips, as well as other possible system/kit components including, but not limited to, one or more bed sheets.

In some embodiments, the disclosed bed sheet retention systems comprise (I) one or more bed sheet retention devices, wherein at least one bed sheet retention device comprises: (A) a side bracket comprising: (a) a horizontally-extending bracket component sized and designed to extend between a bottom surface of a mattress and a support surface under the bottom surface; and (b) one or more sheet-engaging channels connected to said horizontally-extending bracket component, wherein each sheet-engaging channel (1) comprises a sheet-locking member extending along an outer surface of the side bracket, and (2) extends substantially within a plane P parallel with said horizontally-extending bracket component or at an angle A to the plane P parallel with said horizontally-extending bracket component; and (II) one or more sheet locking strips that engage with one or more of the one or more sheet-engaging channels.

In some embodiments, the disclosed bed sheet retention systems (I) a mattress covering component designed and sized to extend over one or more side surfaces of a mattress, wherein the mattress covering component comprises: (A) one or more side sheet portions that extend over one or more side surfaces of a mattress; and (B) one or more sheet-engaging channels extending along the one or more side sheet portions, wherein each sheet-engaging channel comprises a sheet-locking member comprising: (i) an upper (or first) sheet-locking channel member, and (ii) a lower (or second) sheet-locking channel member spaced from the upper sheet-locking channel member, wherein the upper sheet-locking channel member and the lower sheet-locking channel member (a) are designed to engage with one or more sheet-locking strips inserted within the sheet-locking member and between the upper sheet-locking channel member and the lower sheet-locking channel member, and (b) together provide a channel track profile that extends along a given sheet-locking member, wherein the mattress covering component is (1) an integral component of mattress, and forms at least a portion of the one or more side surfaces of mattress, or (2) is separate from and combinable with a mattress so as to cover at least a portion of the one or more side surfaces of mattress; and (II) one or more sheet locking strips that engage with one or more of the one or more sheet-engaging channels.

In some embodiments, the disclosed bed sheet retention systems further comprise (III) one or more accessories, wherein each accessory comprises (a) at least one accessory connecting member, and (b) an accessory body connected to and extending from the at least one accessory connecting member, wherein the at least one accessory connecting

member is configured to extend within and connect to the one or more sheet-engaging channels of the side bracket. In some embodiments, the disclosed bed sheet retention system even further comprise (IV) one or more corner brackets as described in International Patent Application No. PCT/US2023/079473, the subject matter of which is incorporated herein by reference in its entirety.

The present invention is also directed to bed sheet retention systems comprising one or more of the herein-described accessories. In some embodiments, the disclosed bed sheet retention systems comprise (I) one or more bed sheet retention devices, wherein at least one bed sheet retention device comprises: a side bracket comprising: (a) a horizontally-extending bracket component sized and designed to extend between a bottom surface of a mattress and a support surface under the bottom surface; and (b) one or more sheet-engaging channels connected to said horizontally-extending bracket component, wherein each sheet-engaging channel (1) comprises a sheet-locking member extending along an outer surface of the side bracket, and (2) extends substantially within a plane P parallel with said horizontally-extending bracket component or at an angle A to the plane P parallel with said horizontally-extending bracket component; and (II) one or more accessories, wherein each accessory comprises (a) at least one accessory connecting member, and (b) an accessory body connected to and extending from the at least one accessory connecting member, wherein the at least one accessory connecting member is configured to extend within and connect to the one or more sheet-engaging channels of the side bracket.

In other embodiments, the disclosed bed sheet retention systems comprise (I) one or more bed sheet retention devices, wherein at least one bed sheet retention device comprises: a side bracket comprising: (a) a horizontally-extending bracket component sized and designed to extend between a bottom surface of a mattress and a support surface under the bottom surface; and (b) one or more sheet-engaging channels connected to said horizontally-extending bracket component, wherein each sheet-engaging channel (1) comprises a sheet-locking member extending along an outer surface of the side bracket, and (2) extends substantially within a plane P parallel with said horizontally-extending bracket component or at an angle A to the plane P parallel with said horizontally-extending bracket component; (II) one or more sheet locking strips that engage with one or both of the one or more sheet-engaging channels, and (III) one or more accessories, wherein each accessory comprises (a) at least one accessory connecting member, and (b) an accessory body connected to and extending from the at least one accessory connecting member, wherein the at least one accessory connecting member is configured to extend within and connect to the one or more sheet-engaging channels of the side bracket.

In some embodiments, the disclosed bed sheet retention systems (I) a mattress covering component designed and sized to extend over one or more side surfaces of a mattress, wherein the mattress covering component comprises: (A) one or more side sheet portions that extend over one or more side surfaces of a mattress; and (B) one or more sheet-engaging channels extending along the one or more side sheet portions, wherein each sheet-engaging channel comprises a sheet-locking member comprising: (i) an upper (or first) sheet-locking channel member, and (ii) a lower (or second) sheet-locking channel member spaced from the upper sheet-locking channel member, wherein the upper sheet-locking channel member and the lower sheet-locking channel member (a) are designed to engage with one or more sheet-locking strips inserted within the sheet-locking member and between the upper sheet-locking channel member and the lower sheet-locking channel member, and (b) together provide a channel track profile that extends along a given sheet-locking member, wherein the mattress covering component is (1) an integral component of mattress, and forms at least a portion of the one or more side surfaces of mattress, or (2) is separate from and combinable with a mattress so as to cover at least a portion of the one or more side surfaces of mattress; and (II) one or more sheet locking strips that engage with one or more of the one or more sheet-engaging channels.

sheet-locking strips inserted within the sheet-locking member and between the upper sheet-locking channel member and the lower sheet-locking channel member, and (b) together provide a channel track profile that extends along a given sheet-locking member, wherein the mattress covering component is (1) an integral component of mattress, and forms at least a portion of the one or more side surfaces of mattress, or (2) is separate from and combinable with a mattress so as to cover at least a portion of the one or more side surfaces of mattress; (II) one or more sheet locking strips that engage with one or more of the one or more sheet-engaging channels; and (III) one or more accessories, wherein each accessory comprises (a) at least one accessory connecting member, and (b) an accessory body connected to and extending from the at least one accessory connecting member, wherein the at least one accessory connecting member is configured to extend within and connect to the one or more sheet-engaging channels of the mattress covering component.

The present invention is even further directed to methods of making the herein-described bed sheet retention devices, sheet locking strips, and accessories for bed sheet retention devices. In some embodiments, the method of making a bed sheet retention device comprises: forming a bed sheet retention device comprising: a corner bracket comprising: (a) a horizontally-extending bracket component sized and designed to extend between a bottom surface of a mattress and a support surface under the bottom surface; and (b) one or more sheet-engaging channels connected to the horizontally-extending bracket component, wherein each sheet-engaging channel (1) comprises (a) two sheet-locking members, and (b) an open guided section extending around a corner of the corner bracket, and (2) extends substantially within a plane P parallel with the horizontally-extending bracket component or at an angle A to the plane P parallel with said horizontally-extending bracket component, said forming step utilizing one or more steps comprising: one or more thermoforming steps (e.g., a molding steps); one or more machining steps (e.g., one or more drilling, cutting, stamping, sanding, abrading, etc., steps); and one or more assembling steps.

In some embodiments, the method of making a bed sheet retention device comprises: forming a bed sheet retention device comprising: a side bracket comprising: (a) a horizontally-extending bracket component sized and designed to extend between a bottom surface of a mattress and a support surface under the bottom surface; and (b) one or more sheet-engaging channels connected to the horizontally-extending bracket component, wherein each sheet-engaging channel (1) comprises a sheet-locking member extending along an outer surface of the side bracket, and (2) extends substantially within a plane P parallel with said horizontally-extending bracket component or at an angle A to the plane P parallel with said horizontally-extending bracket component, said forming step utilizing one or more steps comprising: one or more thermoforming steps (e.g., a molding steps); one or more machining steps (e.g., one or more drilling, cutting, stamping, sanding, abrading, etc., steps); and one or more assembling steps.

In some embodiments, the method of making a bed sheet retention device comprises: forming a mattress covering component designed and sized to extend over one or more side surfaces of a mattress, wherein the mattress covering component comprises: (A) one or more side sheet portions that extend over one or more side surfaces of a mattress; and (B) one or more sheet-engaging channels extending along the one or more side sheet portions, wherein each sheet-

engaging channel comprises a sheet-locking member comprising: (i) an upper (or first) sheet-locking channel member, and (ii) a lower (or second) sheet-locking channel member spaced from the upper sheet-locking channel member, 5 wherein the upper sheet-locking channel member and the lower sheet-locking channel member (a) are designed to engage with one or more sheet-locking strips inserted within the sheet-locking member and between the upper sheet-locking channel member and the lower sheet-locking channel member, and (b) together provide a channel track profile that extends along a given sheet-locking member. The 10 method may comprise forming the mattress covering component as an integral component of a mattress, so that the mattress covering component forms at least a portion of the one or more side surfaces of mattress. Alternatively, the 15 method may comprise forming the mattress covering component to be separate from and combinable with a mattress so as to cover at least a portion of the one or more side surfaces of mattress.

20 In some embodiments, the method of making an accessory comprises: forming an accessory comprising: (a) at least one accessory connecting member, and (b) an accessory body connected to and extending from the at least one accessory connecting member, wherein the at least one accessory connecting member is configured to extend within and connect to one or more side brackets of a bed sheet retention device, said forming step utilizing one or more steps comprising: one or more thermoforming steps (e.g., a molding steps); one or more machining steps (e.g., one or more drilling, cutting, stamping, sanding, abrading, etc., steps); and one or more assembling steps.

25 The present invention is even further directed to methods of using bed sheet retention devices and accessories with bed sheet retention devices. In some embodiments, the method of using a bed sheet retention device comprises: inserting a horizontally-extending bracket component of the bed sheet retention device between a bottom surface of a mattress and a support surface under the bottom surface; and 30 engaging a sheet material with one or more sheet-engaging channels along a bed sheet retention device, wherein each sheet-engaging channel (1) comprises a sheet-locking member extending along an outer surface of a bracket, and (2) extends substantially within a plane P parallel with the horizontally-extending bracket component or at an angle A to the plane P parallel with said horizontally-extending bracket component, wherein the sheet-locking member comprises (i) an upper sheet-locking channel member, and a 35 lower sheet-locking channel member positioned below and spaced from the upper sheet-locking channel member, wherein each of the upper sheet-locking channel member and the lower sheet-locking channel member are designed to engage with one or more sheet locking strips and/or one or more of the herein-described attachable accessories, said 40 engaging step comprising inserting one or more sheet locking strips and/or one or more of the herein-described attachable accessories between the upper sheet-locking channel member and the lower sheet-locking channel member of the bracket.

45 In some embodiments, the method of using a bed sheet 50 retention device comprises: (I) positioning a mattress covering component so as to extend over one or more side surfaces of a mattress, wherein the mattress covering component comprises: (A) one or more side sheet portions that 55 extend over one or more side surfaces of a mattress; and (B) one or more sheet-engaging channels extending along the one or more side sheet portions, wherein each sheet-engaging channel comprises a sheet-locking member comprising:

(i) an upper (or first) sheet-locking channel member, and (ii) a lower (or second) sheet-locking channel member spaced from the upper sheet-locking channel member, wherein the upper sheet-locking channel member and the lower sheet-locking channel member (a) are designed to engage with one or more sheet-locking strips inserted within the sheet-locking member and between the upper sheet-locking channel member and the lower sheet-locking channel member, and (b) together provide a channel track profile that extends along a given sheet-locking member; and inserting one or more sheet locking strips and/or one or more of the herein-described attachable accessories between the upper sheet-locking channel member and the lower sheet-locking channel member of the mattress covering component.

In some embodiments, the method of using an accessory comprises: connecting an accessory to a corner or side bracket of a bed sheet retention device, the accessory comprising: (a) at least one accessory connecting member, and (b) an accessory body connected to and extending from the at least one accessory connecting member, wherein said connecting step comprises connecting the at least one accessory connecting member of the accessory to the corner or side bracket.

In some embodiments, the method of using an accessory comprises: connecting an accessory to a mattress covering component that extends over one or more side surfaces of a mattress, wherein the mattress covering component comprises: (A) one or more side sheet portions that extend over one or more side surfaces of a mattress; and (B) one or more sheet-engaging channels extending along the one or more side sheet portions, wherein each sheet-engaging channel comprises a sheet-locking member comprising: (i) an upper (or first) sheet-locking channel member, and (ii) a lower (or second) sheet-locking channel member spaced from the upper sheet-locking channel member, wherein the upper sheet-locking channel member and the lower sheet-locking channel member (a) are designed to engage with one or more sheet-locking strips inserted within the sheet-locking member and between the upper sheet-locking channel member and the lower sheet-locking channel member, and (b) together provide a channel track profile that extends along a given sheet-locking member, the accessory comprising: (a) at least one accessory connecting member, and (b) an accessory body connected to and extending from the at least one accessory connecting member, wherein the connecting step comprises connecting the at least one accessory connecting member of the accessory to the mattress covering component.

These and other features and advantages of the present invention will become apparent after a review of the following detailed description of the disclosed embodiments and the appended claims.

BRIEF DESCRIPTION OF THE FIGURES

The present invention is further described with reference to the appended figure, wherein:

FIG. 1 depicts a perspective view of an exemplary bed sheet retention device suitable for use in the disclosed bed sheet retention systems;

FIG. 2 depicts a front right-side view of the exemplary bed sheet retention device shown in FIG. 1;

FIG. 3 depicts a rear left-side view of the exemplary bed sheet retention device shown in FIG. 1;

FIG. 4 depicts a front left-side view of the exemplary bed sheet retention device shown in FIG. 1;

FIG. 5 depicts a rear right-side view of the exemplary bed sheet retention device shown in FIG. 1;

FIG. 6 depicts a top view of the exemplary bed sheet retention device shown in FIG. 1;

5 FIG. 7 depicts a bottom view of the exemplary bed sheet retention device shown in FIG. 1;

10 FIG. 8 depicts another perspective view of the exemplary bed sheet retention device shown in FIG. 1 showing a sheet locking strip positioned to be inserted within an exemplary sheet locking channel of the exemplary bed sheet retention device;

15 FIG. 9 depicts a perspective view of another exemplary bed sheet retention device suitable for use in the disclosed bed sheet retention systems, the exemplary bed sheet retention device comprising two exemplary sheet locking channels as shown;

20 FIG. 10 depicts a perspective view of another exemplary bed sheet retention device suitable for use in the disclosed bed sheet retention systems, the exemplary bed sheet retention device comprising three exemplary sheet locking channels as shown;

25 FIG. 11 depicts another perspective view of the exemplary bed sheet retention device shown in FIG. 10 showing a sheet locking strip positioned to be inserted within a central/middle exemplary sheet locking channel of the exemplary bed sheet retention device;

30 FIG. 12 depicts a perspective view of the exemplary bed sheet retention device shown in FIG. 10 being inserted onto the corner of a mattress;

35 FIG. 13 depicts a front right-side view of the exemplary bed sheet retention device shown in FIG. 10 positioned along corner edges of the mattress shown in FIG. 12;

40 FIG. 14 depicts a side profile view of a sheet locked within an exemplary sheet locking channel of the exemplary bed sheet retention device shown in FIG. 1, 9, or 10 showing a sheet locking strip positioned to be inserted within an upper exemplary sheet locking channel of the exemplary bed sheet retention device;

45 FIG. 15 depicts a side profile view of a sheet locked within an exemplary sheet locking channel of the exemplary bed sheet retention device shown in FIG. 1, 9, or 10 using a sheet locking strip positioned within the exemplary sheet locking channel and over corner portions of the sheet;

50 FIG. 16 depicts a perspective front view of another exemplary bed sheet retention device suitable for use in the disclosed bed sheet retention systems;

55 FIG. 17 depicts a perspective rear view of the exemplary bed sheet retention device shown in FIG. 16;

FIG. 18A depicts a front view of the exemplary bed sheet retention device shown in FIG. 16;

FIG. 18B depicts a top view of the exemplary bed sheet retention device shown in FIG. 16;

FIG. 18C depicts a bottom view of the exemplary bed sheet retention device shown in FIG. 16;

FIG. 19 depicts another front view of the exemplary bed sheet retention device shown in FIG. 1;

FIG. 20 depicts another perspective view of the exemplary bed sheet retention device shown in FIG. 16 showing a sheet locking strip positioned to be inserted within an exemplary sheet locking channel of the exemplary bed sheet retention device;

60 FIG. 21 depicts a perspective front view of another exemplary bed sheet retention device suitable for use in the disclosed bed sheet retention systems, the exemplary bed sheet retention device comprising two exemplary sheet locking channels as shown;

11

FIG. 22 depicts a perspective view of another exemplary bed sheet retention device suitable for use in the disclosed bed sheet retention systems, the exemplary bed sheet retention device comprising three exemplary sheet locking channels as shown, and being inserted along a side surface of a mattress;

FIG. 23 depicts a side profile view of a sheet locked within an exemplary sheet locking channel of the exemplary bed sheet retention device shown in FIG. 16, or 18-22 showing a sheet locking strip positioned to be inserted within an upper exemplary sheet locking channel of the exemplary bed sheet retention device;

FIG. 24 depicts a side profile view of a sheet locked within an exemplary sheet locking channel of the exemplary bed sheet retention device shown in FIG. 16, or 18-22 using a sheet locking strip positioned within the exemplary sheet locking channel and over side portions of the sheet;

FIG. 25A depicts a perspective view of an exemplary accessory suitable for use with the disclosed bed sheet retention devices, and in the disclosed bed sheet retention systems;

FIG. 25B depicts a side view of the exemplary accessory shown in FIG. 25A;

FIG. 26A depicts a perspective view of another exemplary accessory suitable for use with the disclosed bed sheet retention devices, and in the disclosed bed sheet retention systems;

FIG. 26B depicts a side view of the exemplary accessory shown in FIG. 26A;

FIG. 27A depicts a perspective view of another exemplary accessory suitable for use with the disclosed bed sheet retention devices, and in the disclosed bed sheet retention systems;

FIG. 27B depicts a perspective view of an exemplary clamping member suitable for use with the exemplary accessory shown in FIG. 27A;

FIG. 27C depicts a perspective view of an exemplary skirt suitable for use with the exemplary accessory shown in FIG. 27A;

FIG. 27D depicts a close-up view of the exemplary skirt shown in FIG. 27C attached to an outer rim of the exemplary accessory shown in FIG. 27A via the exemplary clamping member shown in FIG. 27B;

FIG. 27E depicts a perspective front view of an exemplary accessory combination comprising the exemplary accessory shown in FIG. 27A with the exemplary skirt shown in FIG. 27C attached to an outer rim thereof via the exemplary clamping member shown in FIG. 27B;

FIG. 28 depicts a side view of another exemplary accessory suitable for use with the disclosed brackets;

FIGS. 29A-29B depict side views of another exemplary accessory suitable for use with the disclosed brackets;

FIG. 30A depicts a perspective view the exemplary corner bracket of FIG. 1 in combination with an inflatable bladder suitable for use with any of the disclosed brackets;

FIGS. 30B-30C depict side views of the exemplary combination shown in FIG. 30A with FIG. 30B showing a view wherein the inflatable bladder is not inflated, and with FIG. 30C showing a view wherein the inflatable bladder is inflated;

FIGS. 31A-31H depict side views of various exemplary accessories suitable for use with the disclosed brackets;

FIG. 32 depicts a perspective view of another exemplary bed sheet retention device suitable for use in the disclosed bed sheet retention systems;

12

FIG. 33 depicts a close-up view of an exemplary sheet-locking member positioned along adjacent side surfaces of the exemplary bed sheet retention device shown in FIG. 32;

FIG. 34 depicts another close-up view of another exemplary sheet-locking member positioned along a side surface of the exemplary bed sheet retention device shown in FIG. 32;

FIG. 35A depicts a perspective view of another exemplary bed sheet retention device suitable for use in the disclosed bed sheet retention systems;

FIG. 35B depicts a perspective view of an exemplary sheet locking strip suitable for use with the bed sheet retention device suitable for use with the exemplary bed sheet retention devices shown in FIGS. 1, 16, 32, and 35A;

FIG. 35C depicts a perspective view of a lower surface of the exemplary bed sheet retention device shown in FIG. 35A;

FIG. 36A depicts a cross-sectional view of the exemplary bed sheet retention device/exemplary sheet-locking member shown in FIGS. 33-35A;

FIG. 36B depicts an exploded view of FIG. 36A;

FIG. 36C depicts a front view of the exemplary sheet-locking member shown in FIGS. 32, and 34-35A;

FIG. 37 depicts a perspective view of the exemplary bed sheet retention device shown in FIG. 33 while in use, securing a sheet onto the exemplary bed sheet retention device via a sheet locking strip;

FIGS. 38A-38B depict a perspective view of another exemplary bed sheet retention device suitable for use in the disclosed bed sheet retention systems;

FIG. 39 depicts a perspective view of another exemplary bed sheet retention device suitable for use in the disclosed bed sheet retention systems;

FIG. 40 depicts a perspective view of another exemplary bed sheet retention device suitable for use in the disclosed bed sheet retention systems; and

FIG. 41 depicts a cross-sectional view of exemplary sheet-locking members embedded within a side surface of a mattress as viewed along lines 41-41 shown in FIG. 40.

The features of the present bed sheet retention devices, bed sheet retention system accessories, and bed sheet retention systems, and methods are set forth in part in the following preferred embodiments. This overview is intended to provide nonlimiting descriptions of the present subject matter and is not intended to provide an exclusive or exhaustive explanation. The preferred embodiments below provide further information about the bed sheet retention devices and systems, and methods of the present invention as described herein.

50 DETAILED DESCRIPTION OF THE INVENTION

The present invention is directed to bed sheet retention devices, bed sheet retention system accessories, and bed sheet retention systems. The bed sheet retention systems and bed sheet retention devices may comprise one or more sheet-connecting members to keep bed sheets fastened to a bed. All of the disclosed designs grip a sheet in a localized individual clamp/connector where the holding forces are directed to each clamp and their teeth/connecting members.

The bed sheet retention devices of the present invention are placed on the corners and/or side edges of a mattress. Depending on the circumstances of the installation, some beds have mattress toppers, thicker and oversized mattresses, as well as smaller and thin mattresses. These circumstances create various scenarios for installing a fitted

13

sheet. Large, oversized mattresses with a mattress topper may use up a great deal of sheeting material, leaving very little to even wrap on the corners and/or sides of the mattress. Then there is the other side of the extreme when the mattress is small, low profile and has an excess of sheeting material. In either scenario, the bed sheet retention devices of the present invention are able to (1) hold down and lock the tight-fitting sheets in place without fear of damaging the material with clamps, and/or (2) take up the excess sheet material and provide a nice snug fit installation.

In some embodiments, the bed sheet retention device of the present invention is slid between the mattress and the supporting foundation. This foundation could be a box spring, wood slats, plywood, or other solid foundation that the mattress rests on top of. The bed sheet retention device is inserted so as to be close to the mattress and encompass a mattress corner and/or a side edge of the mattress.

In other embodiments, the bed sheet retention device of the present invention is positioned so as to cover one or more side edges of a mattress, and in some cases, an upper surface, and a lower surface of the mattress. In these embodiments, the bed sheet retention device is either an integral component of the mattress, or is separate from, but combinable with, a mattress so as to cover one or more side edges of the mattress.

The user can determine which sheet-engaging channel to use given a particular sheeting/bedding arrangement. The sheet-engaging channel or channels also provide options for relaxed or snug fitted sheets. Using the top track results in less material wrap and looser sheets. The bottom track would be the deepest locking distance to provide the most take-up on the sheet. Once the track is selected, the user will pull the fitted sheet over the corner and/or edge of the mattress as well as a given bed sheet retention device.

For an even lock, the user should be sure that the sheet material is located in the same channeling. With the sheet material over the bed sheet retention device, the clear plastic lock stripping is then placed onto the channels landing. This landing sets and stages the material for the track and channel grooves ahead. It takes up the necessary material in order for a smooth entry of the locking strip into the flange track.

Once the strip has entered the locking flange area, the material is then captured and the locking strip exits the locking section. In the case of corner brackets, from here the user can take up more material by folding over the excess corner and then wrapping the locking strip over it following the guides rails along the corner and into the secondary locking flange. This captures the bulk of material and placement of the material on the corner. The sheeting is now locked into place and cannot be removed from the mattress unless the clear locking strips are removed.

One of the unique features of the present invention is the ability to not only lock down the fitted sheet, but the user can lock down the flat sheet. This feature provides the added benefit to those who do not like their sheets pulled from the bottom leaving their feet exposed. This keeps the bottom half of the flat sheet captured. The user can control how much tightness is left in the base of the flat sheet by the amount of take-up that was captured on installing the locking strips.

This process is the same as locking down the fitted sheets with the exception that it will be easier to return to the channel where the fitted sheet is locked down to. The channel will then have 2 locking strips and 2 layers of sheeting. Other channels could be used for the flat sheet, but it is observed that reentering the currently used channel,

14

keep the tool from having to get past 2 layers of free moving sheet material. This could result in hang-ups on some occasions.

A shining feature of the present invention is its ability to work in such tight spaces. There is limited access in many mattress scenarios and being able to guide a semirigid stripping into the blind spots of the mattress is a great bonus to this system. For example, when the bed sheet retention device is a corner bracket, one's hand can be held on the corner to guide the strip into the next locking flange area to capture the blind side of the mattress.

The present invention describes various bed sheet retention device styles and ways to lock material down using a similar approach to the above-described sheet-engaging channels and locking strip. These alternative options include the following:

Option A

This type of locking mechanism uses a male track and relies on a female clip to slide over the male track and lock down the material. This method captures the sides of the sheet material, but does not capture the corners of the material in the same manner as the sliding locking strip does. The clips are also more cosmetically noticeable and not as user friendly as above-described sheet-engaging channels and locking strip.

Option B

Another method uses a slit and a soft rubber material which will push the material into the slit and pinch the material along the slit around the corner.

Option C

This method uses a female track and a male pin. The track on the corner bracket is tapered and the pin is straight. The material is pinned by sliding the pin into the track and locking the sides.

Option D

This method uses an aggressive groove that once the elastic falls into, makes removing it difficult.

Option E

A flexible and soft rubber-like cord could be used to pin the material into a defined groove and lock the entire corner down by pinching and pushing the fabric into the groove and locked into place by the rubber cord.

Option F

This method uses a flexible material that could snap into a track, like the above-described sheet-engaging channels, instead of sliding a locking strip into the track. This method lacks the rigidity of a solid strip running through the channel. The concept could be very much the same except the locking strip snaps from the front instead of slides in from the side.

Option G

This method uses a cord (e.g., elastic, or rigid) that can be fastened to the ends and then the tension of the cord could settle into a predefined groove that it sits in so as to trap the bed sheeting.

15

The present invention is described above and further illustrated below by way of additional embodiments, and examples, which are not to be construed in any way as imposing limitations upon the scope of the invention. On the contrary, it is to be clearly understood that resort may be had to various other embodiments, modifications, and equivalents thereof which, after reading the description herein, may suggest themselves to those skilled in the art without departing from the spirit of the present invention and/or the scope of the appended claims.

Additional Embodiments

Bed Sheet Retention Device Embodiments

1. A bed sheet retention device **100/200** comprising: (I) a bracket **10/40** comprising: (a) a horizontally-extending bracket component **11** sized and designed to extend between a bottom surface **51** of a mattress **50** and a support surface **60** under the bottom surface **51**; and (b) one or more sheet-engaging channels **12** connected to said horizontally-extending bracket component **11**, wherein each sheet-engaging channel **12** (1) comprises a sheet-locking member **13** extending along an outer surface **16/46** of the bracket **10/40**, and (2) extends substantially within a plane **P** parallel with said horizontally-extending bracket component **11** or at an angle **A** to the plane **P** parallel with said horizontally-extending bracket component **11**. In most embodiments, each sheet-engaging channel **12** extends within a plane **P** parallel with said horizontally-extending bracket component **11**; however, in other embodiments, one or more sheet-engaging channels **12** may extend (i) vertically (i.e., 90° to plane **P**), and/or (ii) at any angle **A** from 0 degrees (°) to 90° relative to plane **P** (i.e., +/-any degree between 0° and 90° in increments of 1.0°).

2. The bed sheet retention device **100/200** of embodiment 1, wherein said bracket **10/40** comprises the corner bracket **10** described herein (i.e., in embodiments 9 to 59 below).

3. The bed sheet retention device **100/200** of embodiment 1, wherein said bracket **10/40** comprises the side bracket **40** described herein (i.e., in embodiments 60 to 105 below).

4. The bed sheet retention device **100/200** of any one of embodiments 1 to 3, wherein each of said one or more sheet-locking members **13** comprises (i) an upper sheet-locking channel member **13U**, and (ii) a lower sheet-locking channel member **13L** positioned below and spaced from said upper sheet-locking channel member **13U**, wherein each of said upper sheet-locking channel member **13U** and said lower sheet-locking channel member **13L** are designed to engage with one or more sheet locking strips **30** described herein and/or one or more of the attachable accessories **300** described herein.

5. The bed sheet retention device **100/200** of any one of embodiments 1 to 4, further comprising: (II) one or more sheet locking strips **30** described herein (e.g., in embodiments 47 to 54 below), each sheet locking strip **30** being sized and designed to engage with said one or more sheet-engaging channels **12** of said bracket **10/40**.

6. The bed sheet retention device **100/200** of embodiment 4 or 5, further comprising: (II) one or more sheet locking strips **30** described herein (i.e., in embodiments 47 to 54 below), each sheet locking strip **30** being sized and designed to engage with and be positioned between (i) said upper sheet-locking channel member **13U** and (ii) said lower sheet-locking channel member **13L** of said bracket **10/40**.

7. The bed sheet retention device **100/200** of any one of embodiments 1 to 6, further comprising: (III) one or more

16

accessories **300**, wherein each accessory **300** comprises: (a) at least one accessory connecting member **301**, and (b) an accessory body **302** connected to and extending from the at least one accessory connecting member **301**, wherein the at least one accessory connecting member **301** is configured (i.e., designed) to extend within and connect to the one or more sheet-engaging channels **12** of bracket **10/40**. Suitable accessories **300** include, but are not limited to accessories **300** described below in embodiments 106 to 141.

10. The bed sheet retention device **100/200** of any one of embodiments 4 to 6, further comprising: (III) one or more accessories **300**, wherein each accessory **300** comprises: (a) at least one accessory connecting member **301**, and (b) an accessory body **302** connected to and extending from the at least one accessory connecting member **301**, wherein the at least one accessory connecting member **301** is configured (i.e., designed) to engage with and be positioned between (i) said upper sheet-locking channel member **13U** and (ii) said lower sheet-locking channel member **13L** of said bracket **10/40**. Again, suitable accessories **300** include, but are not limited to accessories **300** described below in embodiments 106 to 141.

vvvvvCorner Bracket Embodiments

25. 9. A bed sheet retention device **100** comprising: (I) a corner bracket **10** comprising: (a) a horizontally-extending bracket component **11** sized and designed to extend between a bottom surface **51** of a mattress **50** and a support surface **60** under the bottom surface **51**; and (b) one or more sheet-engaging channels **12** connected to said horizontally-extending bracket component **11**, wherein each sheet-engaging channel **12** (1) comprises (a) two sheet-locking members **13a/13b**, and (b) an open guided section **14** extending around a corner **15** of the corner bracket **10**, and (2) extends substantially within a plane **P** parallel with said horizontally-extending bracket component **11** or at an angle **A** to the plane **P** parallel with said horizontally-extending bracket component **11**. See, for example, exemplary bed sheet retention device **100** shown in FIGS. 1-8, and plane **P** in FIGS. 2-5.

10. The bed sheet retention device **100** of embodiment 9, wherein each sheet-engaging channel **12** extends substantially within the plane **P** above said horizontally-extending bracket component **11**.

45. 11. The bed sheet retention device **100** of embodiment 9 or 10, wherein said corner bracket **10** further comprises one or more bracket side walls **16** extending from said horizontally-extending bracket component **11** to an upper rim **17** of said corner bracket **10**, and each of the one or more sheet-engaging channels **12** is positioned along one or more outer bracket side wall surfaces **18** of said one or more bracket side walls **16**.

55. 12. The bed sheet retention device **100** of any one of embodiments 9 to 11, wherein said corner bracket **10** further comprises two bracket side walls **16** extending from said horizontally-extending bracket component **11** to an upper rim **17** of said corner bracket **10**, and each of the one or more sheet-engaging channels **10** is positioned along one or more outer bracket side wall surfaces **18** of said two bracket side walls **16**.

60. 13. The bed sheet retention device **100** of embodiment 12, wherein said two bracket side walls **16** are connected to one another at the corner **15** of the corner bracket **10**.

14. The bed sheet retention device **100** of any one of embodiments 9 to 13, wherein said corner bracket **10** further comprises one continuous bracket side wall **16** extending from said horizontally-extending bracket component **11** to

an upper rim 17 of said corner bracket 10, and each of the one or more sheet-engaging channels 12 is positioned along one or more outer bracket side wall surfaces 18 of said one continuous bracket side wall 16. See, for example, exemplary bed sheet retention device 100 shown in FIGS. 1 and 6-13. As shown in FIG. 1, exemplary bed sheet retention device 100 comprises a single, continuous bracket side wall 16 with (1) each of the one or more sheet-engaging channels 12 positioned along opposite substantially straight, perpendicularly-aligned, wall portions, and (2) the open guided section 14 extending along a curved wall portion separating the opposite substantially straight, perpendicularly-aligned, wall portions from one another. See again, FIG. 1.

15. The bed sheet retention device 100 of any one of embodiments 1 to 14, wherein said one or more sheet-engaging channels 12 comprises one to three sheet-engaging channels 12. It should be noted that in some embodiments, each of the one to three sheet-engaging channels 12 may be identical to one another. For example, each of the one to three sheet-engaging channels 12 may have a similar length, height, and depth (e.g., a track profile length L_{TP} , a track profile height H_{TP} , and a track profile width W_{TP}) so as to enable a single sheet, two or more sheets, and/or a comforter to be engaged with/connected to a given sheet-engaging channel 12. In other embodiments, when two or more sheet-engaging channels 12 are present, the two or more sheet-engaging channels 12 may differ from one another. For example, in some embodiments, the two or more sheet-engaging channels 12 independently have lengths, heights and depths (e.g., track profile lengths L_{TP} , track profile heights H_{TP} , and track profile widths W_{TP}) that differ from one sheet-engaging channel 12 to another sheet-engaging channel 12. In this case, a sheet-engaging channel 12 with larger length, height and depth (e.g., a larger track profile length L_{TP} , a larger track profile height H_{TP} , and a larger track profile width W_{TP}) may be used to engage/connect with a comforter, multiple sheets 70, and/or a larger accessory 300, while a sheet-engaging channel 12 with smaller length, height and depth (e.g., a smaller track profile length L_{TP} , a smaller track profile height H_{TP} , and a smaller track profile width W_{TP}) may be used to engage/connect with a single sheet or two sheets, or a smaller accessory 300, using the same bed sheet retention device 100.

16. The bed sheet retention device 100 of any one of embodiments 1 to 15, wherein said one or more sheet-engaging channels 12 comprises one sheet-engaging channel 12.

17. The bed sheet retention device 100 of any one of embodiments 1 to 15, wherein said one or more sheet-engaging channels 12 comprises two sheet-engaging channels 12.

18. The bed sheet retention device 100 of any one of embodiments 1 to 15, wherein said one or more sheet-engaging channels 12 comprises three sheet-engaging channels 12.

19. The bed sheet retention device 100 of any one of embodiments 1 to 18, wherein said horizontally-extending bracket component 11 comprises an outer bracket periphery 19, and (i) at least one aperture 20 extending through the horizontally-extending bracket component 11 within the outer bracket periphery 19, (ii) a cut-out section (not shown) extending through the horizontally-extending bracket component 11 and forming a portion of the outer bracket periphery 19, or (iii) both (i) and (ii). As shown in FIGS. 2-5, the one or more bracket side walls 16 can also have one or more cut-out sections 21 extending through the one or more bracket side walls 16.

20. The bed sheet retention device 100 of any one of embodiments 1 to 19, wherein said horizontally-extending bracket component 11 comprises an outer bracket periphery 19, and at least one aperture 20 extending through the horizontally-extending bracket component 11 within the outer bracket periphery 19.

21. The bed sheet retention device 100 of any one of embodiments 1 to 20, wherein said horizontally-extending bracket component 11 comprises an outer bracket periphery 19, and a single aperture 20 extending through the horizontally-extending bracket component 11 within the outer bracket periphery 19.

22. The bed sheet retention device 100 of any one of embodiments 11 to 21, wherein said horizontally-extending bracket component 11, said one or more bracket side walls 16, and said one or more sheet-engaging channels 12 are integrally connected to one another.

23. The bed sheet retention device 100 of any one of embodiments 11 to 22, wherein said one or more sheet-engaging channels 12 are positioned along said upper rim 17 of said corner bracket 10.

24. The bed sheet retention device 100 of any one of embodiments 9 to 23, wherein said two sheet-locking members 13a/13b comprise (i) a first sheet-engaging channel 13a extending in a first direction d_F along said corner bracket 10, and (ii) a second sheet-engaging channel 13b extending in a second direction d_S along said corner bracket 10, said second direction d_S being substantially perpendicular to and in plane P with said first direction d_F . See, for example, FIG. 6.

25. The bed sheet retention device 100 of embodiment 24, wherein when said horizontally-extending bracket component 11 is positioned between a bottom surface 51 of a mattress 50 and a support surface 60 under the bottom surface 51, the first sheet-engaging channel 13a is positioned to be engageable with a first portion 71 of a sheet 70 extending along the first direction d_F , and the second sheet-engaging channel 13b is positioned to be engageable with a second portion 72 of the sheet 70 extending along the second direction d_S . See, for example, FIG. 15.

30. The bed sheet retention device 100 of any one of embodiments 9 to 25, wherein said two sheet-locking members 13a/13b (1) comprise (i) a first sheet-engaging channel 13a extending in a first direction d_F along said corner bracket 10, and (ii) a second sheet-engaging channel 13b extending in a second direction d_S along said corner bracket 10, said second direction d_S being substantially perpendicular to and in plane P with said first direction d_F , and (2) each of said first sheet-engaging channel 13a and said second sheet-engaging channel 13b independently comprises (i) an upper sheet-locking channel member 13U, and a lower sheet-locking channel member 13L positioned below and spaced from said upper sheet-locking channel member 13U. See, for example, FIGS. 1-3, and 8-9.

35. The bed sheet retention device 100 of embodiment 26, wherein each of said upper sheet-locking channel member 13U and said lower sheet-locking channel member 13L are designed to engage with one or more sheet locking strips 30, or both.

40. The bed sheet retention device 100 of embodiment 26 or 27, wherein each of said upper sheet-locking channel member 13U and said lower sheet-locking channel member 13L are designed to engage with a single sheet locking strip 30.

45. The bed sheet retention device 100 of any one of embodiments 26 to 28, wherein said upper sheet-locking channel member 13U comprises an upper strip engaging member 131 extending towards said lower sheet-locking

channel member 13L, and said lower sheet-locking channel member 13L comprises a lower strip engaging member 132 extending towards said upper sheet-locking channel member 13U. See, for example, FIGS. 2, and 4.

30. The bed sheet retention device 100 of embodiment 29, wherein said upper strip engaging member 131 is separated from said lower strip engaging member 132 by a strip engaging member separation distance d_{SM} that is less than a strip width W_S of a sheet locking strip 30. See, for example, FIGS. 3, and 8.

31. The bed sheet retention device 100 of embodiment 30, wherein said strip engaging member separation distance d_{SM} is greater at a strip inlet 121 of a given sheet-engaging channel 12 (e.g., at an outer entry point 121 at which a locking strip 30 is engaged with said upper strip engaging member 131 and said lower strip engaging member 132 along the corner bracket 10; see, for example, FIG. 2) than at a midpoint 122 along a given sheet-engaging channel (e.g., at a midpoint 122 along said upper strip engaging member 131 and said lower strip engaging member 132 along the corner bracket 10; see, for example, FIGS. 2, and 10-11).

32. The bed sheet retention device 100 of embodiment 30 or 31, wherein said strip engaging member separation distance d_{SM} decreases from a maximum separation distance d_{SMM} at a strip inlet 121 of a given sheet-engaging channel 12 (e.g., at an outer entry point 121 at which a locking strip 30 is engaged with said upper strip engaging member 131 and said lower strip engaging member 132 along the corner bracket 10; see, for example, FIG. 8) to a minimum separation distance d_{SMN} at a location or length 124 along the given sheet-engaging channel 12 (e.g., at a midpoint or midpoint length 124 along said upper strip engaging member 131 and said lower strip engaging member 132 along the corner bracket 10; see, for example, FIG. 2).

33. The bed sheet retention device 100 of embodiment 32, wherein said strip engaging member separation distance d_{SM} increases from the minimum separation distance d_{SMN} at the location or the length 124 along the given sheet-engaging channel 12 to an exit separation distance d_{SME} at a strip outlet 125 of the given sheet-engaging channel 12, said exit separation distance d_{SME} being greater than said minimum separation distance d_{SMN} . See, for example, FIG. 2.

34. The bed sheet retention device 100 of any one of embodiments 11 to 32, wherein each sheet-engaging channel 12' of said one or more sheet-engaging channels 12 further comprises channel side walls 127/128 extending (1) outward from said one or more bracket side walls 16, and (2) along lower and upper edges 137/138 of (a) said two sheet-locking members 13a/13b, and (b) said open guided section 14. See, for example, FIGS. 2 and 5.

35. The bed sheet retention device 100 of embodiment 34, wherein said upper strip engaging member 131 and said lower strip engaging member 132 extend from said channel side walls 127/128 towards one another. See again, FIG. 2.

36. The bed sheet retention device 100 of any one of embodiments 9 to 35, wherein said corner bracket 10 has a bracket length L_B of from about 3.0 inches (in) to about 16.0 in (or any value between 3.0 in and 16.0 in, in increments of 0.1 in, e.g., 8.2 in, or any range of values between 3.0 in and 16.0 in, in increments of 0.1 in, e.g., from 6.6 in to 11.2 in), a bracket width WB of from about 3.0 in to about 16.0 in (or any value between 3.0 in and 16.0 in, in increments of 0.1 in, e.g., 9.3 in, or any range of values between 6.0 in and 16.0 in, in increments of 0.1 in, e.g., from 6.8 in to 10.2 in), and a bracket height H_B of from about 1.5 in to about 12.0 in, in increments of

0.1 in, e.g., 8.7 in, or any range of values between 1.5 in and 12.0 in, in increments of 0.1 in, e.g., from 5.6 in to 8.8 in). See, for example, FIGS. 5 and 7. It should be understood that each corner bracket 10 may have any desired bracket length L_B , and any desired bracket width WB.

37. The bed sheet retention device 100 of any one of embodiments 9 to 36, wherein said corner bracket 10 has a bracket length L_B of from about 6.0 inches (in) to about 9.0 in, a bracket width WB of from about 6.0 in to about 9.0 in, and a bracket height H_B of from about 3.0 in to about 6.0 in.

38. The bed sheet retention device 100 of any one of embodiments 9 to 37, wherein said corner bracket 10 has a bracket length L_B of about 8.5 in, a bracket width WB of about 8.5 in, and a bracket height H_B of about 4.3 in.

39. The bed sheet retention device 100 of any one of embodiments 1 to 38, wherein each of said one or more sheet-engaging channels 12 comprises a track profile having (i) a track profile length L_{TP} of from about 2.5 inches (in) to about 15.5 in (or any value between 2.5 in and 15.5 in, in increments of 0.1 in, e.g., 8.2 in, or any range of values between 2.5 in and 15.5 in, in increments of 0.1 in, e.g., from 4.6 in to 7.2 in), (ii) a track profile height H_{TP} of from about 0.6 in to about 3.0 in (or any value between 0.6 in and 3.0 in, in increments of 0.01 in, e.g., 0.75 in, or any range of values between 0.6 in and 3.0 in, in increments of 0.01 in, e.g., from 0.89 in to 1.65 in), and (iii) a track profile width W_{TP} of from about 0.1 in to about 1.5 in (or any value between 0.1 in and 1.5 in, in increments of 0.01 in, e.g., 0.15 in, or any range of values between 0.1 in and 1.5 in, in increments of 0.01 in, e.g., from 0.16 in to 0.87 in). See, for example, FIG. 14. It should be understood that each of said one or more sheet-engaging channels 12 may independently have a track profile having any desired track profile length L_{TP} , any desired track profile height H_{TP} , and any desired track profile width W_{TP} . As used herein, the term track profile length L_{TP} refers to (a) a track profile length of a single sheet-engaging channel 12, such as shown in exemplary side bracket 40 in FIG. 18A, or (b) a track profile length of the sheet-engaging channels 12 within sheet-locking member 13a and sheet-locking member 13b, such as shown in exemplary corner bracket 10 in FIG. 1.

40. The bed sheet retention device 100 of any one of embodiments 1 to 39, wherein each of said one or more sheet-engaging channels 12 comprises a track profile having (i) a track profile length L_{TP} of from about 3.0 in to about 8.0 in, (ii) a track profile height H_{TP} of about 1.1875 in, and (iii) a track profile width W_{TP} of about 0.1875 in.

41. The bed sheet retention device 100 of any one of embodiments 9 to 40, wherein said corner bracket 10 comprises a polymeric material.

42. The bed sheet retention device 100 of any one of embodiments 9 to 41, wherein said corner bracket 10 comprises a fiber and/or powder/particle filled polymeric material.

43. The bed sheet retention device 100 of embodiment 41 or 42, wherein said polymeric material comprises a polyolefin, an acrylonitrile butadiene styrene copolymer (i.e., an ABS copolymer), a polycarbonate, a polyester, or any combination thereof.

44. The bed sheet retention device 100 of any one of embodiments 41 to 43, wherein said polymeric material comprises a polyolefin, an acrylonitrile butadiene styrene copolymer (i.e., an ABS copolymer), or a combination thereof.

45. The bed sheet retention device **100** of any one of embodiments 41 to 44, wherein said polymeric material comprises an acrylonitrile butadiene styrene copolymer (i.e., an ABS copolymer).

46. The bed sheet retention device **100** of any one of embodiments 42 to 45, wherein said polymeric material is filled with glass fibers and/or glass powder/particles.

47. The bed sheet retention device **100** of any one of embodiments 9 to 46, further comprising: (II) one or more sheet locking strips **30**, each sheet locking strip **30** being sized and designed to engage with said one or more sheet-engaging channels **12** of said corner bracket **10**. It should be understood that each of the one or more sheet locking strips **30** may independently provide one or more additional features to the bed sheet retention device **100**. For example, one or more sheet locking strip **30** may be scented so as to provide a scent into the environment surrounding the bed sheet retention device **100**. Other sheet locking strips **30** may be luminescent so as to provide light into the environment surrounding the bed sheet retention device **100**. Other sheet locking strips **30** could have an attachment material (e.g., hook/loop material, magnet, adhesive, etc.) along an outer surface to attached objects to the sheet locking strip **30**.

48. The bed sheet retention device **100** of any one of embodiments 9 to 47, further comprising: (II) a single sheet locking strip **30** sized and designed to engage with any one sheet-engaging channel **12** within said one or more sheet-engaging channels **12** of said corner bracket **10**.

49. The bed sheet retention device **100** of embodiment 47 or 48, wherein each sheet locking strip **30** has a strip width W_s of from about 0.5 in to about 1.5 in, and a strip thickness T_s of from about 0.05 in to about 0.10 in, and a strip length L_s of from about 4.0 in to about 18.0 in.

50. The bed sheet retention device **100** of any one of embodiments 47 to 49, wherein each sheet locking strip **30** has a strip width W_s of from about 0.8 in to about 1.2 in, and a strip thickness T_s of from about 0.05 in to about 0.08 in, and a strip length L_s of from about 12.0 in to about 16.0 in.

51. The bed sheet retention device **100** of any one of embodiments 47 to 50, wherein each sheet locking strip **30** has a strip width W_s of about 1.0 in, and a strip thickness T_s of about 0.0625 in, and a strip length L_s of about 15.5 in.

52. The bed sheet retention device **100** of any one of embodiments 47 to 51, wherein each sheet locking strip **30** has (1) a 0.5 in radius on each strip corner **31** to make each strip end **32** round, and (2) strip edges **33** that are radiused at about 0.03125 in to provide a smooth finish without corners or edges.

53. The bed sheet retention device **100** of any one of embodiments 47 to 52, wherein each sheet locking strip **30** comprises an acrylic material or a polycarbonate material.

54. The bed sheet retention device **100** of any one of embodiments 47 to 53, wherein each sheet locking strip **30** comprises an acrylic material.

55. A bed sheet retention device **100** comprising: (I) a corner bracket **10** comprising: (a) a horizontally-extending bracket component **11** sized and designed to extend between a bottom surface **51** of a mattress **50** and a support surface **60** under the bottom surface **51**; and (b) two or more sheet-engaging channels **12** connected to said horizontally-extending bracket component **11**, said two or more sheet-engaging channels **12** (1) being separated from one another by a corner **15** of the corner bracket **10**, (2) extending substantially within a plane **P** parallel with said horizontally-extending bracket component **11**, and (3) each independently comprising (i) an upper sheet-locking channel member **13U**, and (ii) a lower sheet-locking channel member **13L**

positioned below and spaced from said upper sheet-locking channel member **13U**, wherein each of said upper sheet-locking channel member **13U** and said lower sheet-locking channel member **13L** are designed to engage with one or more sheet locking strips **30** describe herein and/or one or more of the herein-described attachable accessories **300** describe herein. See, for example, exemplary bed sheet retention device **100** shown in FIGS. 1-8, and plane **P** in FIGS. 2-5.

56. The bed sheet retention device **100** of embodiment 55, wherein said two or more sheet-engaging channels **12** comprises (a) two sheet-locking members **13a/13b**.

57. The bed sheet retention device **100** of embodiment 56, wherein said two sheet-locking members **13a/13b** are separated from one another by (b) an open guided section **14** extending around the corner **15** of the corner bracket **10**.

58. The bed sheet retention device **100** of embodiment 57, wherein said bed sheet retention device **100** comprises one or more features recited in any one of embodiments 1 to 54.

59. The bed sheet retention device **100** of any one of embodiments 9 to 58, further comprising: (III) one or more accessories **300**, wherein each accessory **300** comprises: (a) at least one accessory connecting member **301**, and (b) an accessory body **302** connected to and extending from the at least one accessory connecting member **301**, wherein the at least one accessory connecting member **301** is configured (i.e., designed) to extend within and connect to the one or more sheet-engaging channels **12** of corner bracket **40**.

Side Bracket Embodiments

60. A bed sheet retention device **200** comprising: (I) a side bracket **40** comprising: (a) a horizontally-extending bracket component **11** sized and designed to extend between a bottom surface **51** of a mattress **50** and a support surface **60** under the bottom surface **51**; and (b) one or more sheet-engaging channels **12** connected to said horizontally-extending bracket component **11**, wherein each sheet-engaging channel **12** (1) comprises a sheet-locking member **13** extending along an outer surface **46** of the side bracket **40**, and (2) extends (i) substantially within a plane **P** parallel with said horizontally-extending bracket component **11** or at an angle **A** to the plane **P** parallel with said horizontally-extending bracket component **11**, and (ii) along a side edge (i.e., not a corner) of the mattress **50** and the support surface **60**. See, for example, exemplary bed sheet retention device **100** shown in FIGS. 16-24, and plane **P** in FIG. 18.

61. The bed sheet retention device **200** of embodiment 60, wherein each sheet-engaging channel **12** extends substantially within the plane **P** above said horizontally-extending bracket component **11**.

62. The bed sheet retention device **200** of embodiment 60 or 61, wherein said side bracket **40** further comprises one or more bracket side walls **46** extending from said horizontally-extending bracket component **11** to an upper rim **47** of said side bracket **40**, and each of the one or more sheet-engaging channels **12** is positioned along one or more outer bracket side wall surfaces **48** of said one or more bracket side walls **46**.

63. The bed sheet retention device **200** of any one of embodiments 60 to 62, wherein said side bracket **40** further comprises a single bracket side wall **46** extending from said horizontally-extending bracket component **11** to an upper rim **47** of said side bracket **40**, and each of the one or more sheet-engaging channels **12** is positioned along one or more outer bracket side wall surfaces **48** of said single bracket side wall **46**.

64. The bed sheet retention device **200** of any one of embodiments 60 to 63, wherein said side bracket **40** com-

prises one continuous bracket side wall 46 extending from said horizontally-extending bracket component 11 to an upper rim 47 of said side bracket 40, and each of the one or more sheet-engaging channels 12 is positioned along one or more outer bracket side wall surfaces 48 of said one continuous bracket side wall 46. See, for example, exemplary bed sheet retention device 200 shown in FIGS. 16-24. As shown in FIG. 16, exemplary bed sheet retention device 200/exemplary side bracket 40 comprises a single, continuous bracket side wall 46 with (1) a single sheet-engaging channel 12 positioned along an upper portion of outer bracket side wall surface 48 of said single, continuous bracket side wall 46. It should be noted that although bracket side walls 46 (and bracket side walls 16) are shown as continuous side walls, one or more of bracket side walls 46 (and/or bracket side walls 16) could have one or more apertures (not shown) extending through a given bracket side wall 46 (or bracket side wall 16).

65. The bed sheet retention device 200 of any one of embodiments 60 to 64, wherein said one or more sheet-engaging channels 12 comprises one to three sheet-engaging channels 12. See, for example, bed sheet retention devices 200 shown in FIG. 16-24. It should be noted that in some embodiments, each of the one to three sheet-engaging channels 12 may be identical to one another. For example, each of the one to three sheet-engaging channels 12 may have a similar length, height, and depth (e.g., a track profile length L_{TP} , a track profile height H_{TP} , and a track profile width W_{TP}) so as to enable a single sheet, two or more sheets, and/or a comforter to be engaged with/connected to a given sheet-engaging channel 12. In other embodiments, when two or more sheet-engaging channels 12 are present, the two or more sheet-engaging channels 12 may differ from one another. For example, in some embodiments, the two or more sheet-engaging channels 12 independently have lengths, heights and depths (e.g., track profile lengths L_{TP} , track profile heights H_{TP} , and track profile widths W_{TP}) that differ from one sheet-engaging channel 12 to another sheet-engaging channel 12. In this case, a sheet-engaging channel 12 with larger length, height and depth (e.g., a larger track profile length L_{TP} , a larger track profile height H_{TP} , and a larger track profile width W_{TP}) may be used to engage/connect with a comforter, multiple sheets 70, and/or a larger accessory 300, while a sheet-engaging channel 12 with smaller length, height and depth (e.g., a smaller track profile length L_{TP} , a smaller track profile height H_{TP} , and a smaller track profile width W_{TP}) may be used to engage/connect with a single sheet or two sheets, or a smaller accessory 300, using the same bed sheet retention device 200.

66. The bed sheet retention device 200 of any one of embodiments 60 to 65, wherein said one or more sheet-engaging channels 12 comprises one sheet-engaging channel 12.

67. The bed sheet retention device 200 of any one of embodiments 60 to 65, wherein said one or more sheet-engaging channels 12 comprises two sheet-engaging channels 12.

68. The bed sheet retention device 200 of any one of embodiments 60 to 65, wherein said one or more sheet-engaging channels 12 comprises three sheet-engaging channels 12.

69. The bed sheet retention device 200 of any one of embodiments 60 to 68, wherein said horizontally-extending bracket component 11 comprises an outer bracket periphery 19, and optionally (i) at least one aperture (not shown) extending through the horizontally-extending bracket component 11 within the outer bracket periphery 19, or (ii) at

least one cut-out section 21 extending along and forming a portion of the outer bracket periphery 19, or (iii) both (i) and (ii). Although not shown, the one or more bracket side walls 46 can also have one or more apertures (not shown) and/or cut-out sections 21 extending through the one or more bracket side walls 46. It should be understood that although exemplary horizontally-extending bracket component 11 shown in FIGS. 16-24 has an hour-glass shape, exemplary horizontally-extending bracket component 11 may have any shape as long as the shape provides a desired amount of structural integrity for a particular purpose (e.g., locking one or more sheets 70 in place, supporting one or more accessories 300, or both). For example, exemplary horizontally-extending bracket component 11 could have an overall square or rectangular shape, or a triangular or I-shape, or any other shape. It should also be understood that horizontally-extending bracket component 11 may further comprise one or more features including, but not limited to, (i) an anti-slip coating or layer (not shown) (e.g., a rubber coating or layer) along at least a portion of the lower surface of the horizontally-extending bracket component 11, (ii) an anti-slip coating or layer (not shown) (e.g., a rubber coating or layer) along at least a portion of the upper surface of the horizontally-extending bracket component 11, or (iii) both (i) and (ii).

70. The bed sheet retention device 200 of any one of embodiments 60 to 69, wherein said horizontally-extending bracket component 11 comprises an outer bracket periphery 19, and at least one aperture (not shown) extending through the horizontally-extending bracket component 11 within the outer bracket periphery 19.

71. The bed sheet retention device 200 of any one of embodiments 60 to 70, wherein said horizontally-extending bracket component 11 comprises an outer bracket periphery 19, and a single aperture (not shown) extending through the horizontally-extending bracket component 11 within the outer bracket periphery 19.

72. The bed sheet retention device 200 of any one of embodiments 62 to 71, wherein said horizontally-extending bracket component 11, said one or more bracket side walls 46, and said one or more sheet-engaging channels 12 are integrally connected to one another.

73. The bed sheet retention device 200 of any one of embodiments 62 to 72, wherein said one or more sheet-engaging channels 12 are positioned along said upper rim 47 of said side bracket 40.

74. The bed sheet retention device 200 of any one of embodiments 60 to 73, wherein each of said one or more sheet-locking members 13 comprises (i) an upper sheet-locking channel member 13U, and a lower sheet-locking channel member 13L positioned below and spaced from said upper sheet-locking channel member 13U. See, for example, FIGS. 16, and 19-22.

75. The bed sheet retention device 100 of embodiment 74, wherein each of said upper sheet-locking channel member 13U and said lower sheet-locking channel member 13L are designed to engage with one or more sheet locking strips 30, one or more sheet locking pins (not shown), one or more attachable accessories 300, or any combination thereof. For example, in some embodiments, each of upper sheet-locking channel member 13U and lower sheet-locking channel member 13L are designed to engage with one or more sheet locking strips 30, one or more attachable accessories 300, or any combination thereof.

76. The bed sheet retention device 200 of embodiment 74 or 75, wherein each of said upper sheet-locking channel member 13U and said lower sheet-locking channel member

13L are designed to engage with a single sheet locking strip 30 or a single attachable accessory 300.

77. The bed sheet retention device 200 of any one of embodiments 74 to 76, wherein said upper sheet-locking channel member 13U comprises an upper strip engaging member 131 extending towards said lower sheet-locking channel member 13L, and said lower sheet-locking channel member 13L comprises a lower strip engaging member 132 extending towards said upper sheet-locking channel member 13U. See, for example, FIG. 1, or 3-7.

78. The bed sheet retention device 200 of embodiment 77, wherein said upper strip engaging member 131 is separated from said lower strip engaging member 132 by a strip engaging member separation distance d_{SM} that is less than a strip width W_S of a sheet locking strip 30. See, for example, FIGS. 20, and 22.

79. The bed sheet retention device 200 of embodiment 78, wherein said strip engaging member separation distance d_{SM} is greater at a strip inlet 121 of a given sheet-engaging channel 12 (e.g., at an outer entry point 121 at which a locking strip 30 is engaged with said upper strip engaging member 131 and said lower strip engaging member 132 along the side bracket 40; see, for example, FIG. 17) than at an intermediate point 122 along a length of a given sheet-engaging channel (e.g., at an intermediate point 122 along said upper strip engaging member 131 and said lower strip engaging member 132 along the side bracket 40; see, for example, FIG. 17).

80. The bed sheet retention device 200 of embodiment 78 or 79, wherein said strip engaging member separation distance d_{SM} decreases from a maximum separation distance d_{SMM} at a strip inlet 121 of a given sheet-engaging channel 12 (e.g., at an outer entry point 121 at which a locking strip 30 is engaged with said upper strip engaging member 131 and said lower strip engaging member 132 along the side bracket 40; see, for example, FIG. 3) to a minimum separation distance d_{SMN} at a location or length 124 along the given sheet-engaging channel 12 (e.g., at an intermediate point or intermediate point length 124 along said upper strip engaging member 131 and said lower strip engaging member 132 along the side bracket 10; see, for example, FIG. 19).

81. The bed sheet retention device 200 of embodiment 80, wherein said strip engaging member separation distance d_{SM} increases from the minimum separation distance d_{SMN} at the location or the length 124 along the given sheet-engaging channel 12 to an exit separation distance d_{SME} at a strip outlet 125 of the given sheet-engaging channel 12, said exit separation distance d_{SME} being greater than said minimum separation distance d_{SMM} . See again, for example, FIG. 19.

82. The bed sheet retention device 200 of any one of embodiments 60 to 81, wherein said side bracket 40 has a bracket length L_B of from about 3.0 inches (in) to about 68.0 in (or any value between 3.0 in and 68.0 in, in increments of 0.1 in, e.g., 8.2 in, or any range of values between 3.0 in and 68.0 in, in increments of 0.1 in, e.g., from 6.6 in to 11.2 in), a bracket width WB of from about 3.0 in to about 16.0 in (or any value between 3.0 in and 16.0 in, in increments of 0.1 in, e.g., 9.3 in, or any range of values between 3.0 in and 16.0 in, in increments of 0.1 in, e.g., from 6.8 in to 10.2 in), and a bracket height H_B of from about 1.5 in to about 12.0 in (or any value between 1.5 in and 12.0 in, in increments of 0.1 in, e.g., 8.7 in, or any range of values between 1.5 in and 12.0 in, in increments of 0.1 in, e.g., from 5.6 in to 8.8 in). See, for example, FIGS. 18A-18C. It should be understood

that each side bracket 40 may have any desired bracket length L_B , and any desired bracket width WB , and any desired bracket width H_B .

83. The bed sheet retention device 200 of any one of embodiments 60 to 82, wherein said side bracket 40 has a bracket length L_B of from about 6.0 inches (in) to about 18.0 in, a bracket width WB of from about 6.0 in to about 10.0 in, and a bracket height H_B of from about 3.0 in to about 6.0 in.

10 84. The bed sheet retention device 200 of any one of embodiments 60 to 83, wherein said side bracket 40 has a bracket length L_B of about 16.0 to about 18.0 in, a bracket width WB of about 9.0 in, and a bracket height H_B of about 3.5 in.

15 85. The bed sheet retention device 200 of any one of embodiments 60 to 84, wherein each of said one or more sheet-engaging channels 12 comprises a track profile having (i) a track profile length L_{TP} of from about 2.5 inches (in) to about 67.5 in (or any value between 2.5 in and 67.5 in, in increments of 0.1 in, e.g., 8.2 in, or any range of values between 2.5 in and 67.5 in, in increments of 0.1 in, e.g., from 4.6 in to 7.2 in), (ii) a track profile height H_{TP} of from about 0.6 in to about 3.0 in (or any value between 0.6 in and 3.0 in, in increments of 0.01 in, e.g., 0.75 in, or any range of values between 0.6 in and 3.0 in, in increments of 0.01 in, e.g., from 0.89 in to 1.65 in), and (iii) a track profile width W_{TP} of from about 0.1 in to about 1.5 in (or any value between 0.1 in and 1.5 in, in increments of 0.01 in, e.g., 0.15 in, or any range of values between 0.1 in and 1.5 in, in increments of 0.01 in, e.g., from 0.16 in to 0.87 in). See, for example, FIG. 8. It should be understood that each of said one or more sheet-engaging channels 12 may independently have a track profile having any desired track profile height H_{TP} , and any desired track profile width W_{TP} .

20 86. The bed sheet retention device 200 of any one of embodiments 60 to 85, wherein each of said one or more sheet-engaging channels 12 comprises a track profile having (i) a track profile length L_{TP} of from about 3.5 in to about 16.0 in, (ii) a track profile height H_{TP} of about 1.1875 in, and (iii) a track profile width W_{TP} of about 0.1875 in.

25 87. The bed sheet retention device 200 of any one of embodiments 60 to 86, wherein said side bracket 40 comprises a polymeric material.

30 88. The bed sheet retention device 200 of any one of embodiments 60 to 87, wherein said side bracket 40 comprises a fiber and/or powder/particle filled polymeric material.

89. The bed sheet retention device 200 of embodiment 87 or 88, wherein said polymeric material comprises a polyolefin, an acrylonitrile butadiene styrene copolymer (i.e., an ABS copolymer), a polycarbonate, a polyester, or any combination thereof.

90. The bed sheet retention device 200 of any one of embodiments 87 to 89, wherein said polymeric material comprises a polyolefin, an acrylonitrile butadiene styrene copolymer (i.e., an ABS copolymer), or a combination thereof.

91. The bed sheet retention device 200 of any one of embodiments 87 to 90, wherein said polymeric material comprises an acrylonitrile butadiene styrene copolymer (i.e., an ABS copolymer).

92. The bed sheet retention device 200 of any one of embodiments 88 to 92, wherein said polymeric material is filled with glass fibers and/or glass powder/particles.

93. The bed sheet retention device 200 of any one of embodiments 60 to 92, further comprising: (II) one or more sheet locking strips 30, each sheet locking strip 30 being

sized and designed to engage with said one or more sheet-engaging channels 12 of said side bracket 40.

94. The bed sheet retention device 200 of any one of embodiments 60 to 93, further comprising: (II) a single sheet locking strip 30 sized and designed to engage with any one sheet-engaging channel 12 within said one or more sheet-engaging channels 12 of said side bracket 40.

95. The bed sheet retention device 200 of embodiment 93 or 94, wherein each sheet locking strip 30 has a strip width W_s of from about 0.5 in to about 1.5 in, and a strip thickness T_s of from about 0.05 in to about 0.10 in, and a strip length L_s of from about 4.0 in to about 18.0 in.

96. The bed sheet retention device 200 of any one of embodiments 93 to 95, wherein each sheet locking strip 30 has a strip width W_s of from about 0.8 in to about 1.2 in, and a strip thickness T_s of from about 0.05 in to about 0.08 in, and a strip length L_s of from about 12.0 in to about 16.0 in.

97. The bed sheet retention device 200 of any one of embodiments 93 to 96, wherein each sheet locking strip 30 has a strip width W_s of about 1.0 in, and a strip thickness T_s of about 0.0625 in, and a strip length L_s of about 15.5 in.

98. The bed sheet retention device 200 of any one of embodiments 93 to 97, wherein each sheet locking strip 30 has (1) a 0.5 in radius on each strip corner 31 to make each strip end 32 round, and (2) strip edges 33 that are radiused at about 0.03125 in to provide a smooth finish without corners or edges.

99. The bed sheet retention device 200 of any one of embodiments 93 to 98, wherein each sheet locking strip 30 comprises an acrylic material or a polycarbonate material.

100. The bed sheet retention device 200 of any one of embodiments 93 to 99, wherein each sheet locking strip 30 comprises an acrylic material.

101. A bed sheet retention device 200 comprising: (I) a side bracket 40 comprising: (a) a horizontally-extending bracket component 11 sized and designed to extend between a bottom surface 51 of a mattress 50 and a support surface 60 under the bottom surface 51; and (b) one or more sheet-engaging channels 12 connected to said horizontally-extending bracket component 11, wherein each sheet-engaging channel 12 (1) comprises a sheet-locking member 13 extending along an outer surface 46 of the side bracket 40, (2) extends substantially within a plane P parallel with said horizontally-extending bracket component 11 and (3) each independently comprising (i) an upper sheet-locking channel member 13U, and (ii) a lower sheet-locking channel member 13L positioned below and spaced from said upper sheet-locking channel member 13U, wherein each of said upper sheet-locking channel member 13U and said lower sheet-locking channel member 13L are designed to engage with one or more sheet locking strips 30 describe herein and/or one or more of the herein-described attachable accessories 300 describe herein; and (II) one or more sheet locking strips 30, each of the one or more sheet locking strips 30 being sized and designed to engage with any one sheet-engaging channel 12 within said one or more sheet-engaging channels 12 of said side bracket 40. See, for example, exemplary bed sheet retention device 200 shown in FIGS. 20 and 22 to 23, and plane P in FIG. 18A.

102. The bed sheet retention device 200 of embodiment 101, wherein said one or more sheet-engaging channels 12 comprises a single sheet-locking member 13.

103. The bed sheet retention device 200 of embodiment 101, wherein said one or more sheet-engaging channels 12 comprises two or three sheet-locking members 13 with each sheet-engaging channel 12 being parallel with one another.

104. The bed sheet retention device 200 of any one of embodiments 101 to 103, wherein said bed sheet retention device 200 comprises one or more features recited in any one of embodiments 60 to 100.

105. The bed sheet retention device 100 of any one of embodiments 60 to 104, further comprising: (III) one or more accessories 300, wherein each accessory 300 comprises: (a) at least one accessory connecting member 301, and (b) an accessory body 302 connected to and extending from the at least one accessory connecting member 301, wherein the at least one accessory connecting member 301 is configured (i.e., designed) to extend within and connect to the one or more sheet-engaging channels 12 of the side bracket 10.

Mattress Covering Component Embodiments

106. A mattress covering component 110 designed and sized to extend over one or more side surfaces 52 of a mattress 50, said mattress covering component 10 comprising: (A) one or more side sheet portions 54 that extend over one or more side surfaces 52 of a mattress 50; and (B) one or more sheet-engaging channels 12 extending along the one or more side sheet portions 54, wherein each sheet-engaging channel 12 comprises a sheet-locking member 13 comprising: (i) an upper (or first) sheet-locking channel member 13U, and (ii) a lower (or second) sheet-locking channel member 13L spaced from said upper sheet-locking channel member 13U, wherein said upper sheet-locking channel member 13U and said lower sheet-locking channel member 13L (a) are designed to engage with one or more sheet-locking strips 30 inserted within the sheet-locking member 13 and between the upper sheet-locking channel member 13U and the lower sheet-locking channel member 13L, and (b) together provide a channel track profile that extends along a given sheet-locking member 13, wherein the mattress covering component 110 is (a) an integral component of mattress 50, and forms at least a portion 52' of said one or more side surfaces 52 of mattress 50, or (b) is separate from and combinable with mattress 50 so as to cover at least a portion 52' of the one or more side surfaces 52 of mattress 50. As used herein, the phrase "channel track profile" is used to describe a shape of a given sheet-engaging channel 12 extending along a given sheet-locking member 13 in which one or more sheet-locking strips 30 can be inserted. See, for example, FIGS. 36A-36C. The "channel track profile" includes an overall "channel track profile" length, as well as a "channel track profile" cross-sectional shape at any point along the "channel track profile" length. The "channel track profile" does not include any gap 130 that extends between opposing tip ends of an upper strip engaging member 131 and a lower strip engaging member 132, discussed below. It should be noted that although the gap 130 between opposing tip ends of upper strip engaging member 131 and lower strip engaging member 132 is shown in the figures as having a constant separation distance d_{SM} between the opposing tip ends of upper strip engaging member 131 and lower strip engaging member 132 along a majority of a given sheet-locking member 13 (see, for example, FIG. 36C), the separation distance d_{SM} between opposing tip ends of upper strip engaging member 131 and lower strip engaging member 132 could vary anywhere along a length of a given sheet-locking member 13.

107. The mattress covering component 110 of embodiment 106, wherein said lower sheet-locking channel mem-

ber 13L is positioned below said upper sheet-locking channel member 13U along said one or more side sheet portions 54.

108. The mattress covering component 110 of embodiment 106 or 107, wherein said upper sheet-locking channel member 13U and said lower sheet-locking channel member 13L are positioned along one or more strip portions 133 that extend along said one or more side sheet portions 54. See, for example, in FIG. 33, a close-up view of an exemplary sheet-locking member 13 positioned along adjacent side sheet portions 54 of the exemplary bed sheet retention device 100 shown in FIG. 32. See also, for example, in FIG. 34, another close-up view of another exemplary sheet-locking member 13 positioned along a side sheet portion 54 of the exemplary bed sheet retention device 100 shown in FIG. 32.

109. The mattress covering component 110 of embodiment 108, wherein each strip portion 133 of the one or more strip portions 133 comprises one or more upper sheet-locking channel members 13U and a corresponding number of lower sheet-locking channel members 13L.

110. The mattress covering component 110 of embodiment 108 or 109, wherein each strip portion 133 of the one or more strip portions 133 comprises one upper sheet-locking channel member 13U and a corresponding lower sheet-locking channel members 13L.

111. The mattress covering component 110 of any one of embodiments 108 to 110, wherein each strip portion 133 of the one or more strip portions 133 is surrounded by (e.g., encircled by) said one or more side sheet portions 54.

112. The mattress covering component 110 of any one of embodiments 108 to 111, wherein each strip portion 133 of the one or more strip portions 133 is positioned along said one or more side sheet portions 54 and away from upper and lower edges 55/56 of the mattress covering component 110.

113. The mattress covering component 110 of any one of embodiments 108 to 112, wherein each strip portion 133 of the one or more strip portions 133 is positioned along said one or more side sheet portions 54 and centrally located a substantially equal distance d_1 away from upper and lower edges 55/56 of mattress 50 and/or a substantially equal distance d_2 from upper and lower edges 551/561 of the mattress covering component 110. It should be understood that each of the one or more strip portions 133 may independently be positioned at any distance d_1 away from upper and lower edges 55/56 of mattress 50 and/or any distance d_2 from upper and lower edges 551/561 of the mattress covering component 110 (e.g., d_1 and d_2 independently range from about 0.5 in to about 12.0 in (or any value between 0.5 in and 12.0 in, in increments of 0.1 in, e.g., 3.2 in, or any range of values between 0.5 in and 12.0 in, in increments of 0.1 in, e.g., from 2.5 in to 4.0 in),

114. The mattress covering component 110 of any one of embodiments 108 to 113, wherein said one or more strip portions 133 comprises two or more independent strip portions 133 that, in combination, extend along from one to four side sheet portions 54.

115. The mattress covering component 110 of any one of embodiments 108 to 114, wherein said one or more strip portions 133 comprises a single strip component 133' that extends along all of said one or more side sheet portions 54. See, for example, FIG. 39.

116. The mattress covering component 110 of embodiment 115, wherein said single strip component 133' comprises multiple cut-outs 191 along said single strip component 133' with each cut-out 191 enabling one or more sheet-locking strips 30 to be inserted within said sheet-

locking member 13 and between said upper sheet-locking channel member 13U and said lower sheet-locking channel member 13L positioned along said single strip component 133'. See, for example, FIG. 39.

117. The mattress covering component 110 of any one of embodiments 108 to 116, wherein each strip portion 133 of said one or more strip portions 133 independently has a strip portion length L_{SP} of from about 3.0 inches (in) to about 360.0 in (or any value between 3.0 in and 360.0 in, in increments of 0.1 in, e.g., 8.2 in, or any range of values between 3.0 in and 360.0 in, in increments of 0.1 in, e.g., from 6.6 in to 11.2 in), a strip portion width W_{SP} of from about 0.25 in to about 6.0 in (or any value between 0.25 in and 6.0 in, in increments of 0.1 in, e.g., 3.3 in, or any range of values between 0.25 in and 6.0 in, in increments of 0.1 in, e.g., from 0.5 in to 5.2 in), and a strip portion height H_{SP} of from about 1.0 in to about 8.0 in (or any value between 1.0 in and 8.0 in, in increments of 0.1 in, e.g., 3.0 in, or any range of values between 1.0 in and 8.0 in, in increments of 0.1 in, e.g., from 2.0 in to 3.5 in). For example, when strip portion 133 comprises single strip component 133' (see, FIG. 39), single strip component 133' could have a strip portion length L_{SP} that extends completely around an outer periphery of a mattress 50, and could be from about 120.0 in for a baby bed and up to about 360.0 in for a king-size bed. Typically, when multiple strip portions 133 are used around the periphery of a mattress 50, the strip portions 133 typically independently have a strip portion length L_{SP} of from about 6.0 in to about 18.0 in.

118. The mattress covering component 110 of any one of embodiments 108 to 117, wherein each strip portion 133 of said one or more strip portions 133 independently has a strip portion length L_{SP} of from about 4.0 in to about 16.0 in (or any value between 4.0 in and 16.0 in, in increments of 0.1 in, e.g., 7.2 in, or any range of values between 4.0 in and 16.0 in, in increments of 0.1 in, e.g., from 5.5 in to 11.8 in), a strip portion width W_{SP} of from about 0.5 in to about 3.0 in (or any value between 0.5 in and 3.0 in, in increments of 0.1 in, e.g., 2.3 in, or any range of values between 0.5 in and 3.0 in, in increments of 0.1 in, e.g., from 0.8 in to 2.2 in), and a strip portion height H_{SP} of from about 1.0 in to about 4.0 in (or any value between 1.0 in and 4.0 in, in increments of 0.1 in, e.g., 3.5 in, or any range of values between 1.0 in and 4.0 in, in increments of 0.1 in, e.g., from 2.0 in to 3.5 in).

119. The mattress covering component 110 of any one of embodiments 108 to 118, wherein each strip portion 133 of said one or more strip portions 133 independently has a strip portion length L_{SP} of from about 5.0 in to about 12.0 in (or any value between 5.0 in and 12.0 in, in increments of 0.1 in, e.g., 8.2 in, or any range of values between 5.0 in and 12.0 in, in increments of 0.1 in, e.g., from 5.5 in to 11.8 in), a strip portion width W_{SP} of from about 0.5 in to about 1.5 in (or any value between 0.5 in and 1.5 in, in increments of 0.1 in, e.g., 1.1 in, or any range of values between 0.5 in and 1.5 in, in increments of 0.1 in, e.g., from 0.8 in to 1.2 in), and a strip portion height H_{SP} of from about 1.0 in to about 2.0 in (or any value between 1.0 in and 2.0 in, in increments of 0.1 in, e.g., 1.5 in, or any range of values between 1.0 in and 2.0 in, in increments of 0.1 in, e.g., from 1.0 in to 1.5 in).

120. The mattress covering component 110 of any one of embodiments 106 to 119, wherein each of said one or more sheet-engaging channels 12 comprises a track profile having (i) a track profile length L_{TP} of from about 2.5 inches (in) to about 96.0 in (or any value between 2.5 in and 96.0 in, in increments of 0.1 in, e.g., 8.2 in, or any range of values between 2.5 in and 96.0 in, in increments of 0.1 in, e.g., from 4.6 in to 72.2 in), (ii) a track profile height H_{TP} of from about

0.6 in to about 6.0 in (or any value between 0.6 in and 6.0 in, in increments of 0.01 in, e.g., 0.75 in, or any range of values between 0.6 in and 6.0 in, in increments of 0.01 in, e.g., from 0.89 in to 3.65 in), and (iii) a track profile width W_{TP} of from about 0.1 in to about 1.5 in (or any value between 0.1 in and 1.5 in, in increments of 0.01 in, e.g., 0.15 in, or any range of values between 0.1 in and 1.5 in, in increments of 0.01 in, e.g., from 0.16 in to 0.87 in). See, for example, FIGS. 36A and 36C. It should be understood that each of said one or more sheet-engaging channels 12 may independently have a track profile having any desired track profile length L_{TP} , any desired track profile height H_{TP} , and any desired track profile width W_{TP} . As shown in FIG. 36A, exemplary bed sheet retention device 100/exemplary sheet-locking member 13 secures sheet 70 within the channel track profile of exemplary sheet-locking member 13 with the assistance of exemplary sheet locking strip 30.

121. The mattress covering component 110 of any one of embodiments 106 to 120, wherein each of said one or more sheet-engaging channels 12 comprises a track profile having (i) a track profile length L_{TP} of from about 3.0 in to about 12.0 in (or any value between 3.0 in and 12.0 in, in increments of 0.1 in, e.g., 6.2 in, or any range of values between 3.0 in and 12.0 in, in increments of 0.1 in, e.g., from 4.5 in to 9.8 in), (ii) a track profile height H_{TP} of from 0.5 in to about 3.0 in (or any value between 0.5 in and 3.0 in, in increments of 0.1 in, e.g., 1.5 in, or any range of values between 0.5 in and 3.0 in, in increments of 0.1 in, e.g., from 1.0 in to 1.5 in), and (iii) a track profile width W_{TP} of about 0.1 in to about 1.0 in (or any value between 0.1 in and 1.0 in, in increments of 0.01 in, e.g., 0.15 in, or any range of values between 0.1 in and 1.0 in, in increments of 0.01 in, e.g., from 0.16 in to 0.87 in).

122. The mattress covering component 110 of any one of embodiments 106 to 121, wherein each of said one or more sheet-engaging channels 12 comprises a track profile having (i) a track profile length L_{TP} of from about 4.0 in to about 8.0 in (or any value between 4.0 in and 8.0 in, in increments of 0.1 in, e.g., 6.2 in, or any range of values between 4.0 in and 8.0 in, in increments of 0.1 in, e.g., from 4.5 in to 7.8 in), (ii) a track profile height H_{TP} of from 0.5 in to about 3.0 in (or any value between 1.0 in and 3.0 in, in increments of 0.1 in, e.g., 1.5 in, or any range of values between 1.0 in and 3.0 in, in increments of 0.1 in, e.g., from 1.0 in to 1.5 in), and (iii) a track profile width W_{TP} of about 0.1 in to about 0.3 in (or any value between 0.1 in and 0.3 in, in increments of 0.01 in, e.g., 0.187 in, or any range of values between 0.1 in and 0.3 in, in increments of 0.01 in, e.g., from 0.16 in to 0.27 in).

123. The mattress covering component 110 of any one of embodiments 106 to 122, wherein each of (i) said upper sheet-locking channel member 13U and (ii) said lower sheet-locking channel member 13L independently has a sheet-locking channel member length LM_L of from about 3.0 in to about 12.0 in (or any value between 3.0 in and 12.0 in, in increments of 0.1 in, e.g., 6.2 in, or any range of values between 3.0 in and 12.0 in, in increments of 0.1 in, e.g., from 4.5 in to 9.8 in), a sheet-locking channel member width LM_W of from about 0.3 in to about 4.0 in (or any value between 0.3 in and 4.0 in, in increments of 0.1 in, e.g., 0.5 in, or any range of values between 0.3 in and 4.0 in, in increments of 0.1 in, e.g., from 0.4 in to 1.2 in), a sheet-locking channel member height LM_H of from about 0.25 in to about 2.0 in (or any value between 0.25 in and 2.0 in, in increments of 0.01 in, e.g., 0.37 in, or any range of values between 0.25 in and 2.0 in, in increments of 0.01 in, e.g., from 0.35 in to 1.25 in), and a sheet-locking channel member thickness LM_T of from about 0.1 in to about 1.0 in

(or any value between 0.1 in and 1.0 in, in increments of 0.01 in, e.g., 0.12 in, or any range of values between 0.1 in and 1.0 in, in increments of 0.01 in, e.g., from 0.12 in to 0.25 in). See, for example, FIGS. 36B-36C.

124. The mattress covering component 110 of any one of embodiments 106 to 123, wherein each of (i) said upper sheet-locking channel member 13U and (ii) said lower sheet-locking channel member 13L independently has a sheet-locking channel member length LM_L of from about 4.0 in to about 8.0 in (or any value between 4.0 in and 8.0 in, in increments of 0.1 in, e.g., 6.2 in, or any range of values between 4.0 in and 8.0 in, in increments of 0.1 in, e.g., from 4.5 in to 7.8 in), a sheet-locking channel member width LM_W of from about 0.3 in to about 2.0 in (or any value between 0.3 in and 2.0 in, in increments of 0.01 in, e.g., 1.3 in, or any range of values between 0.3 in and 2.0 in, in increments of 0.01 in, e.g., from 0.8 in to 1.2 in), a sheet-locking channel member height LM_H of from about 0.4 in to about 1.0 in (or any value between 0.35 in and 1.0 in, in increments of 0.01 in, e.g., 0.38 in, or any range of values between 0.35 in and 1.0 in, in increments of 0.01 in, e.g., from 0.38 in to 0.48 in), and a sheet-locking channel member thickness LM_T of from about 0.05 in to about 0.5 in (or any value between 0.05 in and 0.5 in, in increments of 0.01 in, e.g., 0.07 in, or any range of values between 0.05 in and 0.5 in, in increments of 0.01 in, e.g., from 0.10 in to 0.15 in).

125. The mattress covering component 110 of any one of embodiments 106 to 124, wherein each sheet-engaging channel 12 of said one or more sheet-engaging channels 12 comprises an upper channel side wall 127 and a lower channel side wall 128 extending outward from said one or more side sheet portions 54 (i.e., opposite an outer side surface of the mattress covering component 10), and away from said one or more side sheet portions 54 (i.e., opposite an outer side surface of the mattress covering component 110), and (2) forming portions of said upper sheet-locking channel member 13U and said lower sheet-locking channel member 13L.

126. The mattress covering component 10 of embodiment 125, wherein (a) said upper sheet-locking channel member 13U further comprises an upper strip engaging member 131 extending downward from said upper channel side wall 127 and towards said lower sheet-locking channel member 13L, and (b) said lower sheet-locking channel member 13L comprises a lower strip engaging member 132 extending upward from said lower channel side wall 128 and towards said upper sheet-locking channel member 13U. As shown in FIG. 36B, exemplary sheet-engaging channel 12 comprises a channel track profile that is bound by (i) an inner surface 145 of upper channel side wall 127, (ii) an inner surface 146 of lower channel side wall 128, (iii) an inner surface 147 of upper strip engaging member 131, (iv) an inner surface portion of gap 130, (v) an inner surface 148 of lower strip engaging member 132, and (v) an inner surface 149 opposite gap 130. As further shown in FIG. 36B, exemplary sheet-engaging channel 12 comprises a channel track profile that has a substantially rectangular cross-sectional shape, wherein the track profile height H_{TP} is greater than a track profile width W_{TP} , and the track profile height H_{TP} is constant along the track profile width W_{TP} . However, it should be understood that sheet-engaging channels 12 suitable for use in the sheet-locking members 13 present invention may have any desired channel track profile with any desired cross-sectional shape. For example, although not

shown, channel track profiles could have a cross-sectional pill shape, or a cross-sectional oval shape, or other cross-sectional shape.

127. The mattress covering component **110** of any one of embodiments 106 to 126, wherein the channel track profile has a cross-sectional shape at a given point along a length of a given sheet-locking member **13**, said cross-sectional shape being a cross-sectional rectangular shape, or a cross-sectional pill shape, or a cross-sectional oval shape.

128. The mattress covering component **110** of any one of embodiments 106 to 127, wherein the channel track profile has a cross-sectional rectangular shape, or a cross-sectional pill shape.

129. The mattress covering component **110** of any one of embodiments 106 to 128, wherein the channel track profile has a cross-sectional shape in which a track profile height H_{TP} is greater than a track profile width W_{TP} of the channel track profile.

130. The mattress covering component **110** of any one of embodiments 106 to 129, wherein the channel track profile has a cross-sectional shape in which a track profile height H_{TP} is $2\times$ greater than a track profile width W_{TP} of the channel track profile.

131. The mattress covering component **110** of any one of embodiments 106 to 130, wherein the channel track profile has a cross-sectional shape in which a track profile height H_{TP} is from $2\times$ greater to about $8\times$ greater than a track profile width W_{TP} of the channel track profile (or any multiple between $2\times$ and $8\times$ in increments of $0.1\times$).

132. The mattress covering component **110** of any one of embodiments 106 to 131, wherein the channel track profile has a cross-sectional shape that is symmetrical along opposite sides of a channel dissecting line LD extending through the channel track profile and parallel with said one or more side sheet portions **54**. See again, FIG. 36B.

133. The mattress covering component **10** of any one of embodiments 125 to 132, wherein the channel track profile is bound by (i) an inner surface **145** of upper channel side wall **127**, (ii) an inner surface **146** of lower channel side wall **128**, (iii) an inner surface **147** of upper strip engaging member **131**, (iv) an inner surface portion of gap **130**, (v) an inner surface **148** of lower strip engaging member **132**, and (v) an inner surface **149** opposite gap **130**. See, FIG. 36B.

134. The mattress covering component **110** of any one of embodiments 106 to 133, wherein said upper sheet-locking channel member **13U** comprises an upper outermost member surface **157** opposite said one or more side sheet portions **54** (i.e., opposite an outer side surface of the mattress covering component **110**), and said lower sheet-locking channel member **13L** further comprises a lower outermost member surface **158** opposite said one or more side sheet portions **54** (i.e., opposite an outer side surface of the mattress covering component **110**), wherein a majority of a surface area of each of said upper outermost member surface **157** and said lower outermost member surface **158** is within a first plane P_1 that is parallel with a second plane P_2 in which said one or more side sheet portions **54** (i.e., an outer side surface of the mattress covering component **110**) extends. See again, FIG. 36B.

135. The mattress covering component **10** of embodiment 134, wherein (a) said upper strip engaging member **131** provides said upper outermost member surface **157**, and (b) said lower strip engaging member **132** provides said lower outermost member surface **158**.

136. The mattress covering component **110** of any one of embodiments 106 to 135, wherein said one or more side sheet portions **54** extend over two or more side surfaces **52** of mattress **50**.

137. The mattress covering component **110** of any one of embodiments 106 to 136, wherein said one or more side sheet portions **54** extend over three or more side surfaces **52** of mattress **50**.

138. The mattress covering component **110** of any one of embodiments 106 to 137, wherein said one or more side sheet portions **54** extend over all four side surfaces **52** of mattress **50**.

139. The mattress covering component **110** of any one of embodiments 106 to 138, wherein said one or more side sheet portions **54** extend over $>30\%$ of a total surface area SA_{SSM} of said one or more side surfaces **52** of a mattress **50**.

140. The mattress covering component **110** of any one of embodiments 106 to 139, wherein said one or more side sheet portions **54** extend over a majority (i.e., $>50\%$) of a total surface area SA_{SSM} of said one or more side surfaces **52** of a mattress **50**.

141. The mattress covering component **110** of any one of embodiments 106 to 140, wherein said one or more side sheet portions **54** extend over all of a total surface area SA_{SSM} of said one or more side surfaces **52** of a mattress **50**.

142. The mattress covering component **110** of any one of embodiments 106 to 141, wherein said mattress covering component **110** only covers a portion or all of said one or more side surfaces **52** of mattress **50**, and does not cover an upper surface **57** or a lower surface **58** of mattress **50**. See, for example, exemplary mattress covering component **110** in the form of a band/circular component shown in FIGS. 38A-38B.

143. The mattress covering component **110** of any one of embodiments 106 to 141, further comprising an upper sheet portion **59** that extends over an upper surface **57** of mattress **50**.

144. The mattress covering component **110** of any one of embodiments 106 to 141 and 143, further comprising an upper sheet portion **59** that extends over a majority (i.e., $>50\%$) of an upper surface **57** of mattress **50**.

145. The mattress covering component **110** of any one of embodiments 106 to 141 and 143 to 144, further comprising an upper sheet portion **59** that extends over all of an upper surface **57** of mattress **50**. See, for example, exemplary mattress covering component **110** in the form of a mattress **50** shown in FIG. 32. See also, for example, exemplary mattress covering component **110** in the form of a mattress cover **120** shown in FIGS. 35A and 35C.

146. The mattress covering component **110** of any one of embodiments 143 to 145, wherein said upper sheet portion **59** is attached to said one or more side sheet portions **54**.

147. The mattress covering component **110** of any one of embodiments 106 to 141 and 143 to 146, further comprising a lower sheet portion **501** that extends over a lower (or bottom) surface **58** of mattress **50**.

148. The mattress covering component **110** of any one of embodiments 106 to 141 and 143 to 147, further comprising a lower sheet portion **501** that extends over a majority (i.e., $>50\%$) of a lower (or bottom) surface **58** of mattress **50**.

149. The mattress covering component **110** of any one of embodiments 106 to 141 and 143 to 148, further comprising a lower sheet portion **501** that extends over all of a lower (or bottom) surface **58** of mattress **50**. See, for example, exemplary mattress covering component **110** in the form of a mattress **50** shown in FIG. 32. See also, for example,

exemplary mattress covering component 110 in the form of a mattress cover 120 shown in FIGS. 35A and 35C.

150. The mattress covering component 110 of any one of embodiments 147 to 149, wherein said lower sheet portion 501 is attached to said one or more side sheet portions 14.

151. The mattress covering component 110 of any one of embodiments 147 to 150, wherein said lower sheet portion 16 is attached to said upper sheet portion 15.

152. The mattress covering component 110 of any one of embodiments 106 to 141 and 143 to 151, wherein said mattress covering component 110 is sized so as to encapsulate mattress 50 within the mattress covering component 110. See again, for example, exemplary mattress covering component 110 in the form of a mattress cover 120 shown in FIGS. 35A and 35C.

153. The mattress covering component 110 of any one of embodiments 106 to 141 and 143 to 152, wherein said mattress covering component 110 further comprises a zipper 117 along said mattress covering component 110, said zipper 117 being designed to enable mattress 50 to be inserted within the mattress covering component 110 thru an opening (not shown) provided by the zipper 117 when in an unzipped position (not shown). See again, for example, exemplary mattress covering component 110 in the form of a mattress cover 120 with exemplary zipper 117 shown in FIG. 35C.

154. The mattress covering component 110 of any one of embodiments 106 to 153, wherein said mattress covering component 110 comprises one or more sheet-engaging channels 12 along two or more side sheet portions 54. For example, two adjacent side sheet portions 54 (i.e., extending along perpendicular sides of a mattress corner) can each independently have one or more sheet-engaging channels 12 thereon.

155. The mattress covering component 110 of any one of embodiments 106 to 154, wherein said mattress covering component 110 comprises one or more sheet-engaging channels 12 along three or more side sheet portions 54. For example, side sheet portions 54 along (i) the foot end of a mattress 50 and (ii) opposite sides of the mattress 50 can each independently have one or more sheet-engaging channels 12 thereon.

156. The mattress covering component 110 of any one of embodiments 106 to 155, wherein said mattress covering component 110 comprises one or more sheet-engaging channels 12 along each of the one or more side sheet portions 54. For example, all side sheet portions 54 along (i) the foot end of a mattress 50, (ii) opposite sides of the mattress 50, and (iii) the head end of the mattress 50 can each independently have one or more sheet-engaging channels 12 thereon.

157. The mattress covering component 110 of any one of embodiments 106 to 156, wherein said mattress covering component 110 comprises two or more sheet-engaging channels 12 along each of the one or more side sheet portions 54 (i.e., along each of the one or more mattress sides 52). Although not shown, it should be understood that the two or more sheet-engaging channels 12 extending along a side sheet portion 54 of mattress covering component 110 could comprise two or more sheet-engaging channels 12 parallel and aligned with one another similar to the parallel and aligned sheet-engaging channels 12 shown in FIGS. 10-13 and 21-22.

158. The mattress covering component 110 of any one of embodiments 106 to 157, wherein said mattress covering component 110 comprises at least two sheet-engaging channels 12 that are normal to one another (i.e., oriented at

substantially a 90° angle to one another) along two adjacent side sheet portions 54 (i.e., along mattress sides 52 in a corner of mattress 50).

159. The mattress covering component 110 of any one of embodiments 106 to 158, wherein said mattress covering component 110 comprises at least two sheet-engaging channels 12 that are parallel to one another along opposite side sheet portions 54 of said mattress covering component 110 (i.e., along opposite sides 52 of mattress 50 or mattress cover 120).

160. The mattress covering component 110 of any one of embodiments 106 to 159, wherein said mattress covering component 110 comprises two or more sheet-engaging channels 12 that are parallel to one another and positioned above one other along a given side sheet portion 54 of said mattress covering component 110 (i.e., a multi-channel configuration similar to the multi-channel configurations shown in FIGS. 9-13, and 21-22).

161. The mattress covering component 110 of any one of embodiments 143 to 160, wherein said mattress covering component 110 further comprises one or more sheet-engaging channels 12 extending along the upper sheet portion 59 of said mattress covering component 110.

162. The mattress covering component 110 of any one of embodiments 147 to 161, wherein said mattress covering component 110 further comprises one or more sheet-engaging channels 12 extending along the lower sheet portion 501 of said mattress covering component 110.

163. The mattress covering component 110 of any one of embodiments 106 to 162, wherein said one or more side sheet portions 54 each independently comprises a fabric material, a film material, or a combination of fabric material and film material.

164. The mattress covering component 110 of any one of embodiments 106 to 163, wherein said one or more side sheet portions 54 each independently comprises a fabric material.

165. The mattress covering component 110 of any one of embodiments 106 to 164, wherein said one or more side sheet portions 54 each independently comprise a fabric material, said fabric material comprising a woven fabric, a knit fabric, a nonwoven fabric, a unidirectional fabric, or any combination thereof.

166. The mattress covering component 110 of any one of embodiments 106 to 165, wherein said one or more side sheet portions 54 each independently comprises a fabric material, said fabric material comprising a nonwoven fabric. Suitable nonwoven fabrics include, but are not limited to, spunbonded nonwovens, spunlaced nonwovens, meltblown nonwovens, stitch bonded nonwovens, unidirectional fabric nonwovens, or any combination thereof.

167. The mattress covering component 110 of any one of embodiments 106 to 166, wherein said one or more side sheet portions 54 each independently comprises a film material. It should be noted that in some embodiments, the mattress covering component 110 may comprise one or more side sheet portions 54 that comprise a film material with no fabric material present. In other embodiments, the mattress covering component 110 may comprise one or more side sheet portions 54 that comprise a film material in combination with a fabric material.

168. The mattress covering component 110 of any one of embodiments 106 to 167, wherein said one or more side sheet portions 54 each independently comprise a film material, said film material comprising polyethylene, polypropylene, polyester, polyvinyl chloride, or any combination thereof.

169. The mattress covering component **110** of any one of embodiments 106 to 168, wherein said one or more side sheet portions **54** each independently comprise an amount of elasticity such that said one or more side sheet portions **54**, in combination, have (1) an overall length L_{LPO} when in an undisturbed state (i.e., no pulling force thereon), and (2) an overall disturbed length L_{LPD} when in a disturbed state (i.e., a pulling force is applied thereon), and said overall disturbed length L_{LPD} is greater than said overall length L_{LPO} . See, for example, exemplary mattress covering component **110** shown in FIGS. 38A-38B with FIG. 38A showing exemplary mattress covering component **110** with length L_{LPO} in an undisturbed state, and FIG. 38B showing exemplary mattress covering component **110** with length L_{LPD} in a disturbed (i.e., stretched) state along the four side surfaces **52** of mattress **50**.

170. The mattress covering component **110** of embodiment 169, wherein said one or more side sheet portions **54**, in combination, returns to the overall length L_{LPO} from the said overall disturbed length L_{LPD} when a pulling force is removed from said one or more side sheet portions **54**.

171. The mattress covering component **110** of any one of embodiments 143 to 170, wherein said upper sheet portion **59** comprises a fabric material, said fabric material comprising a woven fabric, a knit fabric, a nonwoven fabric, a unidirectional fabric, or any combination thereof.

172. The mattress covering component **110** of any one of embodiments 143 to 171, wherein said upper sheet portion **59** comprises a fabric material, said fabric material comprising a nonwoven fabric. Suitable nonwoven fabrics include, but are not limited to, spunbonded nonwovens, spunlaced nonwovens, meltblown nonwovens, stitch bonded nonwovens, unidirectional fabric nonwovens, or any combination thereof.

173. The mattress covering component **110** of any one of embodiments 143 to 172, wherein said upper sheet portion **59** comprises a film material. It should be noted that in some embodiments, the mattress covering component **110** may comprise upper sheet portion **59** that comprises a film material with no fabric material present. In other embodiments, the mattress covering component **110** may comprise upper sheet portion **59** that comprises a film material in combination with a fabric material.

174. The mattress covering component **110** of any one of embodiments 143 to 173, wherein said upper sheet portion **59** comprises a film material, said film material comprising polyethylene, polypropylene, polyester, polyvinyl chloride, or any combination thereof.

175. The mattress covering component **110** of any one of embodiments 147 to 174, wherein said lower sheet portion **501** comprises a fabric material, said fabric material comprising a woven fabric, a knit fabric, a nonwoven fabric, a unidirectional fabric, or any combination thereof.

176. The mattress covering component **110** of any one of embodiments 147 to 175, wherein said lower sheet portion **501** comprises a fabric material, said fabric material comprising a nonwoven fabric. Suitable nonwoven fabrics include, but are not limited to, spunbonded nonwovens, spunlaced nonwovens, meltblown nonwovens, stitch bonded nonwovens, unidirectional fabric nonwovens, or any combination thereof.

177. The mattress covering component **110** of any one of embodiments 147 to 176, wherein said lower sheet portion **501** comprises a film material. It should be noted that in some embodiments, the mattress covering component **110** may comprise lower sheet portion **501** that comprises a film material with no fabric material present. In other embodiments,

ments, the mattress covering component **110** may comprise lower sheet portion **501** that comprises a film material in combination with a fabric material.

178. The mattress covering component **110** of any one of embodiments 147 to 177, wherein said lower sheet portion **501** comprises a film material, said film material comprising polyethylene, polypropylene, polyester, polyvinyl chloride, or any combination thereof.

179. The mattress covering component **110** of any one of embodiments 106 to 151 and 154 to 178, wherein said mattress covering component **110** is an integral component of mattress **50**, and forms at least a portion **52'** of said one or more side surfaces **52** of mattress **50**.

180. The mattress covering component **110** of any one of embodiments 106 to 178, wherein said mattress covering component **110** is separate from and combinable with mattress **50** so as to cover at least a portion **52'** of the one or more side surfaces **52** of mattress **50**.

181. The mattress covering component **110** of any one of embodiments 106 to 178 and 180, wherein said mattress covering component **110** is a mattress cover **120** that is sized to cover mattress **50**.

182. A mattress **50** comprising the mattress covering component **110** of any one of embodiments 106 to 151 and 154 to 179, wherein said mattress covering component **110** forms one or more outer surfaces of the mattress **50** (i.e., any portion or all of the one or more sides **52** of mattress **50**). See again, exemplary mattress covering component **110** in the form of mattress **50** shown in FIG. 32.

183. The mattress covering component **110** of any one of embodiments 106 to 181 or the mattress **50** of embodiment 182, further comprising: (III) one or more sheet locking strips **30**, each sheet locking strip **30** being sized and designed to engage with said sheet-locking member **13** of said one or more sheet-engaging channels **12**. See, for example, exemplary sheet locking strip **30** shown in FIG. 35B. Sheet locking strips **30** suitable for use with the mattress covering component **110** are described above with used with corner bracket **10**, and/or side bracket **40**.

184. The mattress covering component **110** of any one of embodiments 106 to 181 or the mattress **50** of embodiment 182 to 183, wherein each sheet locking strip **30** is sized and designed to extend between (i) said upper sheet-locking channel member **13U**, and (ii) said lower sheet-locking channel member **13L** of said mattress covering component **10**.

185. The mattress covering component **110** of any one of embodiments 106 to 181 or the mattress **50** of embodiment 182 to 184, wherein at least one sheet locking strip **30** of said one or more sheet locking strips **30** provides a fragrance, said fragrance being coated on and/or incorporated in said at least one sheet locking strip **30**.

186. The mattress covering component **110** of any one of embodiments 106 to 181 or the mattress **50** of embodiment 182 to 185, further comprising: (IV) one or more accessories **300**, each accessory **300** being sized and designed to engage with said sheet-locking member **13** of said one or more sheet-engaging channels **12**.

187. The mattress covering component **110** or mattress **50** of embodiment 186, wherein each accessory **300** is sized and designed to extend between (i) said upper sheet-locking channel member **13U**, and (ii) said lower sheet-locking channel member **13L** of said mattress covering component **110**.

188. The mattress covering component **110** or mattress **50** of embodiment 186 or 187, wherein at least one accessory **300** of said one or more accessory **300** provides a fragrance,

said fragrance being coated on and/or incorporated in and/or housed within said at least one accessory 300.

Mattress Cover Embodiments

189. A mattress cover 120 designed and sized to extend over one or more side surfaces 52 of a mattress 50, said mattress cover 120 comprising: (A) one or more side sheet portions 54 that extend over one or more side surfaces 52 of a mattress 50; and (B) one or more sheet-engaging channels 12 extending along the one or more side sheet portions 54, wherein each sheet-engaging channel 12 comprises a sheet-locking member 13 comprising: (i) an upper (or first) sheet-locking channel member 13U, and (ii) a lower (or second) sheet-locking channel member 13L spaced from said upper sheet-locking channel member 13U, wherein said upper sheet-locking channel member 13U and said lower sheet-locking channel member 13L (a) are designed to engage with one or more sheet-locking strips 30 inserted within the sheet-locking member 13 and between the upper sheet-locking channel member 13U and the lower sheet-locking channel member 13L, and (b) together provide a channel track profile that extends along a given sheet-locking member 13, wherein the mattress cover 120 is separate from and combinable with a mattress 50 so as to cover at least a portion 52' of the one or more side surfaces 52 of mattress 50.

190. The mattress cover 120 of embodiment 189, wherein the mattress cover 120 comprises one or more features/ additional components described in one or more of any one of embodiments 106 to 188.

191. The mattress cover 120 of embodiment 189, wherein the one or more side sheet portions 54 of the mattress cover 120 extend over one or more side surfaces 52 of a mattress 50.

192. The mattress cover 120 of any one of embodiments 189 to 191, wherein the one or more side sheet portions 54 of the mattress cover 120 extend over three or more side surfaces 52 of a mattress 50.

193. The mattress cover 120 of any one of embodiments 189 to 192, wherein the one or more side sheet portions 54 of the mattress cover 120 extend over all four side surfaces 52 of a mattress 50.

194. The mattress cover 120 of any one of embodiments 189 to 193, wherein the mattress cover 120 extends over an upper surface 57 of a mattress 50.

195. The mattress cover 120 of any one of embodiments 189 to 194, wherein the mattress cover 120 extends over a lower surface 58 of a mattress 50.

196. The mattress cover 120 of any one of embodiments 189 to 195, wherein each of the one or more sheet-engaging channels 12 independently has a channel profile as described in one or more of any one of embodiments 120 to 135, and/or, for example, as shown in FIGS. 35A to 36C.

Mattress Embodiments

197. A mattress 50 comprising: (A) one or more side sheet portions 54 that extend over and form at least a portion of one or more side surfaces 52 of the mattress 50; and (B) one or more sheet-engaging channels 12 extending along the one or more side sheet portions 54, wherein each sheet-engaging channel 12 comprises a sheet-locking member 13 comprising: (i) an upper (or first) sheet-locking channel member 13U, and (ii) a lower (or second) sheet-locking channel member 13L spaced from said upper sheet-locking channel member 13U, wherein said upper sheet-locking channel member 13U and the lower sheet-locking channel member 13L (a) are designed to engage with one or more sheet-locking strips 30 inserted within the sheet-locking member 13 and between the upper sheet-locking channel member 13U and the lower sheet-locking channel member 13L, and (b) together provide a channel track profile that extends along a given sheet-locking member 13, wherein the one or more side sheet portions 54 are integral component(s) of the mattress 50, and form at least a portion 52' of said one or more side surfaces 52 of the mattress 50.

198. The mattress 50 of embodiment 197, wherein the mattress 50 comprises one or more features/additional components described in one or more of any one of embodiments 106 to 151, 154 to 179, and 182 to 188.

199. The mattress 50 of embodiment 197 or 198, wherein the one or more side sheet portions 54 of the mattress cover 120 extend over all four side surfaces 52 of the mattress 50.

200. The mattress 50 of any one of embodiments 197 to 199, wherein said upper sheet-locking channel member 13U comprises an upper outermost member surface 157 that extends outward from a side surface 52 of the mattress 50, and said lower sheet-locking channel member 13L further comprises a lower outermost member surface 158 that extends outward from the side surface 52 of the mattress 50, wherein a majority of a surface area of each of said upper outermost member surface 157 and said lower outermost member surface 158 is within a first plane P₁ that is parallel with a second plane P₂ in which said side surface 52 extends. See again, FIG. 36B.

201. The mattress 50 of any one of embodiments 197 to 199, wherein said upper sheet-locking channel member 13U comprises an upper outermost member surface 157 that extends along a side surface 52 of the mattress 50, and said lower sheet-locking channel member 13L further comprises a lower outermost member surface 158 that extends along the side surface 52 of the mattress 50, wherein each of said upper outermost member surface 157 and said lower outermost member surface 158 is either (i) within a second plane P₂ in which said side surface 52 extends, or (ii) embedded within mattress 50 so as not to extend beyond side surface 52 (i.e., not thru second plane P₂). See, for example, the exemplary configuration shown in FIGS. 40-41.

202. The mattress 50 of any one of embodiments 197 to 199 and 201, wherein said upper sheet-locking channel member 13U comprises an upper outermost member surface 157 that extends along a side surface 52 of the mattress 50, and said lower sheet-locking channel member 13L further comprises a lower outermost member surface 158 that extends along the side surface 52 of the mattress 50, wherein each of said upper outermost member surface 157 and said lower outermost member surface 158 is within a second plane P₂ in which said side surface 52 extends. See again, for example, the configuration shown in FIGS. 40-41.

203. A mattress 50 comprising: one or more sheet-engaging channels 12 extending along and embedded within one or more side surfaces 52 of the mattress 50, wherein each sheet-engaging channel 12 comprises a sheet-locking member 13 comprising: (i) an upper (or first) sheet-locking channel member 13U, and (ii) a lower (or second) sheet-locking channel member 13L spaced from said upper sheet-locking channel member 13U, wherein said upper sheet-locking channel member 13U and said lower sheet-locking channel member 13L (a) are designed to engage with one or more sheet-locking strips 30 inserted within the sheet-locking member 13 and between the upper sheet-locking channel member 13U and the lower sheet-locking channel

member 13L, and (b) together provide a channel track profile that extends along a given sheet-locking member 13.

204. The mattress 50 of embodiment 203, wherein said upper sheet-locking channel member 13U comprises an upper outermost member surface 157 that extends along the one or more side surfaces 52 of the mattress 50, and said lower sheet-locking channel member 13L further comprises a lower outermost member surface 158 that extends along the a side surface 52 of the mattress 50, wherein each of said upper outermost member surface 157 and said lower outermost member surface 158 is either (i) within a second plane P_2 in which said side surface 52 extends, or (ii) embedded within mattress 50 so as not to extend beyond side surface 52 (i.e., not thru second plane P_2). See, for example, the configuration shown in FIGS. 40-41. When the upper sheet-locking channel member 13U and the lower sheet-locking channel member 13L are embedded within mattress 50, the upper sheet-locking channel member 13U and the lower sheet-locking channel member 13L may be components of a molded part (not shown) that is sized to fit (i) within a correspondingly sized opening (not shown) within a side surface 52 of mattress 50 (i.e., through a side sheet portion 54 of mattress 50) or (ii) within a correspondingly sized molded part (not shown) positioned along and within a side surface 52 of mattress 50. Embedded sheet-locking members 13, similar to the exemplary sheet-locking members 13 shown in FIGS. 40-41, could be along a side surface 52 of mattress 50 (i.e., instead of or in addition to a side bracket 40) and/or within a corner of a mattress 50 (i.e., instead of or in addition to a corner bracket 10).

205. The mattress 50 of embodiment 203 or 204, wherein said upper sheet-locking channel member 13U comprises an upper outermost member surface 157 that extends along a side surface 52 of the mattress 50, and said lower sheet-locking channel member 13L further comprises a lower outermost member surface 158 that extends along the side surface 52 of the mattress 50, wherein each of said upper outermost member surface 157 and said lower outermost member surface 158 is within a second plane P_2 in which said side surface 52 extends. See again, for example, the configuration shown in FIGS. 40-41.

206. The mattress 50 of any one of embodiments 203 to 205, wherein the mattress 50 comprises one or more features/additional components described in one or more of any one of embodiments 106 to 151, 154 to 179, and 182 to 188.

207. The mattress 50 of any one of embodiments 203 to 206, wherein each of the one or more sheet-engaging channels 12 independently has a channel profile as described in one or more of any one of embodiments 120 to 135, and/or, for example, as shown in FIGS. 35A to 36C and 40 to 41.

Mattress Band Embodiments

208. A mattress band 110' designed and sized to extend over one or more side surfaces 52 of a mattress 50, said mattress band 110' comprising: (A) one or more side sheet portions 54 that extend over one or more side surfaces 52 of a mattress 50; and (B) one or more sheet-engaging channels 12 extending along the one or more side sheet portions 54, wherein each sheet-engaging channel 12 comprises a sheet-locking member 13 comprising: (i) an upper (or first) sheet-locking channel member 13U, and (ii) a lower (or second) sheet-locking channel member 13L spaced from said upper sheet-locking channel member 13U, wherein said upper sheet-locking channel member 13U and said lower sheet-locking channel member 13L (a) are designed to

engage with one or more sheet-locking strips 30 inserted within the sheet-locking member 13 and between the upper sheet-locking channel member 13U and the lower sheet-locking channel member 13L, and (b) together provide a channel track profile that extends along a given sheet-locking member 13, wherein the mattress band 110' is separate from and combinable with a mattress 50 so as to cover at least a portion 52' of the one or more side surfaces 52 of mattress 50. See again, exemplary mattress band 110' shown in FIGS. 38A-38B.

209. The mattress band 110' of embodiment 208, wherein the mattress band 110' comprises one or more features/additional components described in one or more of any one of embodiments 106 to 142, 154 to 160, 163 to 170, 180, and 183 to 188.

210. The mattress band 110' of embodiment 208 or 209, wherein the one or more side sheet portions 54 of the mattress band 110' extend over all four side surfaces 52 of a mattress 50.

211. The mattress band 110' of any one of embodiments 208 to 210, wherein each of the one or more sheet-engaging channels 12 independently has a channel profile as described in one or more of any one of embodiments 120 to 135, and/or, for example, as shown in FIGS. 35A to 36C.

Mattress Covering Strip Portion Embodiments

212. A mattress covering strip portion 133 designed and sized to extend over one or more side surfaces 52 of a mattress 50, said mattress covering strip portion 133 comprising: (A) one or more strip portions 133 that extend over one or more side surfaces 52 of a mattress 50; and (B) one or more sheet-engaging channels 12 extending along the strip portions 133, wherein each sheet-engaging channel 12 comprises a sheet-locking member 13 comprising: (i) an upper (or first) sheet-locking channel member 13U, and (ii) a lower (or second) sheet-locking channel member 13L spaced from said upper sheet-locking channel member 13U, wherein said upper sheet-locking channel member 13U and said lower sheet-locking channel member 13L (a) are designed to engage with one or more sheet-locking strips 30 inserted within the sheet-locking member 13 and between the upper sheet-locking channel member 13U and the lower sheet-locking channel member 13L, and (b) together provide a channel track profile that extends along a given sheet-locking member 13, wherein the mattress covering strip portion 133 is separate from and combinable with a mattress 50 so as to cover at least a portion 52' of the one or more side surfaces 52 of mattress 50. See again, exemplary mattress covering strip portion 133' shown in FIG. 39.

213. The mattress covering strip portion 133 of embodiment 212, wherein the mattress covering strip portion 133 comprises one or more features/additional components described in one or more of any one of embodiments 107 to 110, 114 to 135, 142, and 183 to 188.

214. The mattress covering strip portion 133 of embodiment 212 or 213, wherein the mattress covering strip portion 133 extend over all four side surfaces 52 of a mattress 50.

215. The mattress covering strip portion 133 of any one of embodiments 212 to 214, wherein the mattress covering strip portion 133 comprises a single strip component 133'.

216. The mattress covering strip portion 133 of embodiment 215, wherein said single strip component 133' comprises multiple cut-outs 191 along said single strip component 133' with each cut-out 191 enabling one or more sheet-locking strips 30 to be inserted within said sheet-locking member 13 and between said upper sheet-locking

channel member 13U and said lower sheet-locking channel member 13L positioned along said single strip component 133'. See again, for example, FIG. 39.

217. The mattress covering strip portion 133 of any one of embodiments 212 to 216, wherein said mattress covering strip portion 133 is a continuous loop (i.e., similar to exemplary mattress covering component 110/110' shown in FIGS. 38A-38B.

218. The mattress covering strip portion 133 of any one of embodiments 212 to 216, wherein said mattress covering strip portion 133 is a non-continuous loop with fasteners 134/135 at opposite ends of said non-continuous loop to fasten said mattress covering strip portion 133 into a loop. See again, for example, FIG. 39.

219. The mattress covering strip portion 133 of any one of embodiments 212 to 218, wherein each of the one or more sheet-engaging channels 12 independently has a channel profile as described in one or more of any one of embodiments 120 to 135, and/or, for example, as shown in FIGS. 35A to 36C.

Accessories Embodiments

220. An accessory 300 comprising: (a) at least one accessory connecting member 301, and (b) an accessory body 302 connected to and extending from the at least one accessory connecting member 301, wherein the at least one accessory connecting member 301 is configured (i.e., designed) to extend within and connect to one or more sheet-engaging channels 12 of (1) a bracket 10/40 of a bed sheet retention device 100/200 or (2) a mattress covering component 110 or (3) a mattress cover 120 or (4) a mattress 50 or (5) a mattress band 110' or (6) a mattress covering strip portion 133 (i.e., as described in embodiments 106 to 219) so as to position at least a portion of said accessory body 302 (i) above the one or more sheet-engaging channels 12, and/or (ii) below the one or more sheet-engaging channels 12, and/or (iii) within a horizontal plane P containing the one or more sheet-engaging channels 12.

221. The accessory 300 of embodiment 220, wherein said at least one accessory connecting member 301 comprises a single accessory connecting member 301. See, for example, exemplary accessories 300 shown in FIGS. 10A-10B.

222. The accessory 300 of embodiment 220, wherein said at least one accessory connecting member 301 comprises two or more accessory connecting members 301. See, for example, exemplary accessories 300 shown in FIGS. 11A-11B.

223. The accessory 300 of any one of embodiments 220 to 222, wherein each of said at least one accessory connecting member 301 comprises a vertically-extending connecting strip component 303 attached to said accessory body 302.

224. The accessory 300 of any one of embodiments 220 to 223, wherein each of said at least one accessory connecting member 301 comprises a vertically-extending connecting strip component 303 attached to said accessory body 302 via one or more intermediate connecting members 304. See, for example, exemplary accessories 300 shown in FIGS. 10A-11B.

225. The accessory 300 of embodiment 224, wherein each vertically-extending connecting strip component 303 has a connecting strip component width W_{CSC} of from about 0.1 in to about 1.5 in (or any value between 0.1 in and 1.5 in, in increments of 0.01 in, e.g., 0.52 in, or any range of values between 0.1 in and 1.5 in, in increments of 0.01 in, e.g., from 0.59 in to 1.35 in), and a connecting strip component

thickness T_{CSC} of from about 0.25 in to about 3.0 in (or any value between 0.25 in and 3.0 in, in increments of 0.01 in, e.g., 0.52 in, or any range of values between 0.25 in and 3.0 in, in increments of 0.01 in, e.g., from 0.59 in to 1.65 in), and a connecting strip component length L_{CSC} of from about 2.0 in to about 18.0 in (or any value between 2.0 in and 18.0 in, in increments of 0.01 in, e.g., 3.5 in, or any range of values between 2.0 in and 18.0 in, in increments of 0.01 in, e.g., from 3.80 in to 5.65 in).

226. The accessory 300 of embodiment 224 or 225, wherein each vertically-extending connecting strip component 303 has a connecting strip component width W_{CSC} of from about 0.8 in to about 1.2 in, and a connecting strip component thickness T_{CSC} of from about 0.05 in to about 0.08 in, and a connecting strip component length L_{CSC} of from about 4.0 in to about 12.0 in.

227. The accessory 300 of any one of embodiments 224 to 226, wherein each vertically-extending connecting strip component 303 has a connecting strip component width W_{CSC} of about 1.0 in, and a connecting strip component thickness T_{CSC} of about 0.0625 in, and a connecting strip component length L_{CSC} of about 5.5 in.

228. The accessory 300 of any one of embodiments 224 to 227, wherein each vertically-extending connecting strip component 303 has (1) a 0.5 in radius on each connecting strip component corner to make each connecting strip end 305 round, and (2) connecting strip edges 306 that are radiused at about 0.03125 in to provide a smooth finish without corners or edges.

229. The accessory 300 of any one of embodiments 224 to 228, wherein each of (i) said at least one accessory connecting member 301, (ii) said accessory body 302, and (iii) said one or more intermediate connecting members 304 independently comprises a polymeric material with or without fillers/reinforcements. Suitable fillers/reinforcements include, but are not limited to, glass fibers, glass powder/particles, carbon fibers, aramid fibers, other polymeric fibers, one or more fabrics (e.g., woven fabrics, nonwoven fabrics, etc.) made from any of the herein-described materials, or any combination thereof.

230. The accessory 300 of any one of embodiments 224 to 229, wherein each of (i) said at least one accessory connecting member 301, (ii) said accessory body 302, and (iii) said one or more intermediate connecting members 304 independently comprises a polymeric material with fillers/reinforcements therein.

231. The accessory 300 of any one of embodiments 224 to 230, wherein each of (i) said at least one accessory connecting member 301, (ii) said accessory body 302, and (iii) said one or more intermediate connecting members 304 independently comprises an acrylic material or a polycarbonate material.

232. The accessory 300 of any one of embodiments 224 to 231, wherein each of (i) said at least one accessory connecting member 301, (ii) said accessory body 302, and (iii) said one or more intermediate connecting members 304 independently comprises an acrylic material.

233. The accessory 300 of any one of embodiments 224 to 232, wherein each of (i) said at least one accessory connecting member 301, (ii) said accessory body 302, and (iii) said one or more intermediate connecting members 304 independently comprises glass fibers, glass powder/particles, and/or one or more glass fiber containing fabrics.

234. The accessory 300 of any one of embodiments 220 to 233, wherein said accessory body 302 is connected to said at least one accessory connecting member 301 so that a portion or all of said accessory body 302 is positioned above

said at least one accessory connecting member 301. See, for example, exemplary accessory 300 in FIG. 28.

235. The accessory 300 of any one of embodiments 220 to 234, wherein said accessory body 302 is connected to said at least one accessory connecting member 301 so that a portion or all of said accessory body 302 is positioned below said at least one accessory connecting member 301.

236. The accessory 300 of any one of embodiments 220 to 235, wherein said accessory body 302 comprises an accessory body surface 308 that is structurally capable of supporting an object (not shown) resting on and/or connected to the accessory body surface 308.

237. The accessory 300 of any one of embodiments 220 to 236, wherein said accessory body 302 comprises an accessory body surface 308 that is structurally capable of supporting an object (not shown) resting on and/or connected to the accessory body surface 308, wherein the object comprises one or more of a book, a drink container (e.g., a cup or glass or bottle), a food container (e.g., a plate of food), a computer pad, a laptop computer, a cell phone, a lamp, a television remote, an air freshener, a picture frame, vehicle keys, etc., or any combination thereof.

238. The accessory 300 of any one of embodiments 220 to 237, wherein a position of said accessory body 302 relative to said at least one accessory connecting member 301 is adjustable within a horizontal plane PH. For example, the accessory body 302 can be moved towards or away from the at least one accessory connecting member 301 within a given horizontal plane PH.

239. The accessory 300 of any one of embodiments 220 to 238, wherein a position of said accessory body 302 relative to said at least one accessory connecting member 301 is adjustable within a vertical plane P_V . For example, the accessory body 302 can be moved up or down relative to the at least one accessory connecting member 301 within a given horizontal plane PH.

240. The accessory 300 of any one of embodiments 220 to 239, wherein a position of said accessory body 302 relative to said at least one accessory connecting member 301 is adjustable within a horizontal plane PH and a vertical plane P_V .

241. The accessory 300 of any one of embodiments 224 to 240, wherein said one or more intermediate connecting members 304 comprises a connecting arm 307 extending between said accessory body 302 and said at least one accessory connecting member 301.

242. The accessory 300 of any one of embodiments 224 to 241, wherein said one or more intermediate connecting members 304 comprises a jointed connecting arm 307 extending between said accessory body 302 and said at least one accessory connecting member 301, said jointed connecting arm 307 (a) comprising one or more joints 309, and (b) enabling movement of said accessory body 302 so that a position of said accessory body 302 relative to said at least one accessory connecting member 301 is adjustable within (i) a horizontal plane PH, (ii) a vertical plane P_V , or (iii) both a horizontal plane PH, and a vertical plane P_V . See, for example, exemplary accessory 300 shown in FIGS. 29A-29B, wherein a portion of said accessory body 302 (e.g., accessory body surface 308) is positioned within a storage range D_{RS} (i.e., a portion of accessory body 302 (e.g., accessory body surface 308) is within the range D_{RS} shown in FIG. 29A during storage), but may be positioned anywhere within use range D_{RU} shown in FIG. 29B).

243. The accessory 300 of any one of embodiments 224 to 242, wherein at least one joint 309 of said one or more joints 309 comprises a joint 309' that allows rotation of a

portion of said accessory body 302 (e.g., accessory body surface 308) along a line extending through the joint 309'. See again, for example, exemplary accessory 300 shown in FIG. 29B with joint 309' proximate accessory body surface 308.

244. The accessory 300 of any one of embodiments 220 to 240, wherein said accessory body 302 comprises one or more features selected from: (i) a ledge or rim 313 (see, FIG. 27A) extending along an accessory body surface 308 of said accessory body 302, (ii) a hole 311 extending through an accessory body surface 308 of said accessory body 302, (iii) a clip or clamping member (not shown) suitable for fastening an object (e.g., a book, a phone, a computer pad or tablet, etc.) to an accessory body surface 308 of said accessory body 302, (iv) a clothes hanger for hanging one or more items of clothing (not shown), (v) a towel rack for hanging one or more towels (not shown), (vi) a scented or scent-generating component to provide a scent in the area near accessory body 302, (vii) a cup-/glass-holding feature (see, exemplary cup-holding accessory 300 shown in FIGS. 26A-26B, and exemplary cup-holder accessory 300 holding cup 342 shown in FIG. 31C, (viii) a bedside holster (i.e., for a hand gun or long gun), (ix) a bedside light/lamp 341 as shown in FIG. 31A or FIG. 31B, a fan 346 as shown in FIG. 31D, an articulated arm 347 as shown in FIG. 31E, a scent pod 348 as shown in FIG. 31F, a bed railing 349 as shown in FIG. 31G, a kickstand component 346 as shown in FIG. 31H, or any combinations thereof. It should be noted that any of the above-described accessories 300 could further comprise another sheet-engaging channel 12 along an outer surface of the accessory 300 similar to kickstand component 346 shown in FIG. 31H. For example, fan 346 shown in FIG. 31D could have a sheet-engaging channel 12 along body accessory 302 opposite the accessory connecting member 301. Such configurations can result in parallel sheet-engaging channels 12 within a horizontal plane such as horizontally-extending plane P.

245. The accessory 300 of any one of embodiments 220 to 244, wherein said accessory body 302 comprises one or more electronic components therein and/or thereon (not shown), the one or more electronic components comprising one or more of (i) a phone charging outlet, (ii) a 120V outlet (e.g., a standard home outlet), (iii) a music-generating device (e.g., a music speaker and/or Bluetooth component), (iv) a television screen or computer screen, (v) a charging pad (i.e., induction charging), and/or (vi) a medical device (e.g., to monitor a patient, to display patient information, etc.).

246. The accessory 300 of any one of embodiments 220 to 245, wherein said accessory body 302 has an accessory body width W_{AB} of from about 0.5 in to about 18.0 in, an accessory body length L_{AB} of from about 0.5 in to about 24.0 in, and an accessory body thickness T_{AB} of from about 0.25 in to about 12.0 in, depending on the overall shape and configuration of the accessory body 302. For example, when the accessory body 302 comprises a bedside tabletop accessory 300, such as shown in FIGS. 25A-25B, the accessory body 302 will typically have a larger accessory body width W_{AB} , a larger accessory body length L_{AB} , and a smaller accessory body thickness T_{AB} when compared to the accessory body 302 of cup-holding accessory 300 shown in FIGS. 26A-26B. It should be understood that a given accessory body 302 can have any desired accessory body width W_{AB} , any desired accessory body length L_{AB} , and any desired accessory body thickness T_{AB} as long as the resulting accessory body 302 is supported by the at least one accessory

connecting member 301 positioned within the one or more sheet-engaging channels 12 of bracket 10/40 of bed sheet retention device 100/200.

247. The accessory 300 of any one of embodiments 220 to 246, wherein said accessory body 302 has an accessory body width W_{AB} of from about 4.0 in to about 14.0 in, an accessory body length L_{AB} of from about 4.0 in to about 16.0 in, and an accessory body thickness T_{AB} of from about 0.5 in to about 6.0 in, depending on the overall shape and configuration of the accessory body 302.

248. The accessory 300 of any one of embodiments 220 to 247, wherein said accessory body 302 has an accessory body width W_{AB} of from about 6.0 in to about 12.0 in, an accessory body length L_{AB} of from about 6.0 in to about 12.0 in, and an accessory body thickness T_{AB} of from about 0.5 in to about 3.0 in, depending on the overall shape and configuration of the accessory body 302.

249. The accessory 300 of any one of embodiments 220 to 248, wherein said accessory body 302 comprises an accessory body surface 308 having an accessory body outer periphery 315, and one or more accessory body connectors 314 positioned along said accessory body outer periphery 315, said one or more accessory body connectors 314 enabling connection of one or more accessory body components to said accessory body 302. See, for example, exemplary accessory 300 shown in FIG. 27A.

250. The accessory 300 of embodiment 249, wherein said one or more accessory body connectors 314 comprises a single accessory body connector 314 extending along said accessory body outer periphery 315.

251. The accessory 300 of embodiment 249 or 250, further comprising one or more attachable connectors 316, each of the one or more attachable connectors 316 being designed to attach/connect to and detach/disconnect from said one or more accessory body connectors 314. See, for example, exemplary accessory 300 and exemplary attachable connector 316 shown in FIGS. 27A-27B.

252. The accessory 300 of any one of embodiments 249 to 251, further comprising one or more attachable materials 318, each of the one or more materials 318 being designed to attach/connect to and detach/disconnect from said one or more accessory body connectors 314 via one or more attachable connectors 316. See, for example, exemplary attachable material 318, namely, skirt 318, shown in FIG. 27C. Also, see exemplary accessory 300 in FIG. 27D-27E, wherein exemplary attachable material 318, namely, skirt 318, is attached to single accessory body connector 314 along accessory body outer periphery 315 via attachable connector 316. As shown in this embodiment, attachable connector 316 clamps over a portion of skirt 318 onto single accessory body connector 314 of accessory body 302.

253. The accessory 300 of any one of embodiments 220 to 252, wherein said accessory 300 is attached to a bracket 10/40 of a bed sheet retention device 100/200 so as to position at least a portion of said accessory body 302 (i) above the one or more sheet-engaging channels 12, and/or (ii) below the one or more sheet-engaging channels 12, and/or (iii) within a horizontal plane P containing the one or more sheet-engaging channels 12.

254. The accessory 300 of any one of embodiments 220 to 253, wherein said accessory 300 is attached to a bracket 10/40 comprising the corner bracket 10 described in embodiments 9 to 59.

255. The accessory 300 of any one of embodiments 220 to 253, wherein said accessory 300 is attached to a bracket 10/40 comprising the side bracket 40 described in embodiments 60 to 105.

256. The accessory 300 of any one of embodiments 220 to 253, wherein said accessory 300 is attached to the mattress covering component 110 described in embodiments 106 to 188.

257. The accessory 300 of any one of embodiments 220 to 253, wherein said accessory 300 is attached to the mattress cover 120 described in embodiments 189 to 196.

258. The accessory 300 of any one of embodiments 220 to 253, wherein said accessory 300 is attached to the mattress 50 described in embodiments 197 to 207.

259. The accessory 300 of any one of embodiments 220 to 253, wherein said accessory 300 is attached to the mattress band 110' described in embodiments 208 to 211.

260. The accessory 300 of any one of embodiments 220 to 253, wherein said accessory 300 is attached to the mattress covering strip portion 133 described in embodiments 212 to 219.

Bed Sheet Retention Systems and Kit Embodiments

261. A bed sheet retention system (or kit) 1000 comprising: (I) at least one of (A) one or more of the herein-described brackets 10/40, (B) one or more of the herein-described mattress covering components 110, (C) one or more of the herein-described mattress covers 120, (D) one or more of the herein-described mattresses 50, (E) one or more of the herein-described mattress bands 110', and (F) one or more of the herein-described mattress covering strip portions 133; and (II) one or more of the herein-described sheet locking strips 30.

262. The bed sheet retention system (or kit) 1000 of embodiment 261, wherein the system (or kit) 1000 comprises one or more brackets 10/40 comprising at least one corner bracket 10 as described in embodiments 9 to 59.

263. The bed sheet retention system (or kit) 1000 of embodiment 262, wherein the at least one corner bracket 10 comprises four or more corner brackets 10.

264. The bed sheet retention system (or kit) 1000 of any one of embodiments 261 to 263, wherein the system (or kit) 1000 comprises at least one side bracket 40 as described in embodiments 60 to 105.

265. The bed sheet retention system (or kit) 1000 of embodiment 264, wherein said at least one side bracket 40 comprises two or more side brackets 40 (e.g., from 2 to 8 side brackets 40).

266. The bed sheet retention system (or kit) 1000 of any one of embodiments 261 to 265, wherein the system (or kit) 1000 comprises at least one of the herein-described mattress covering components 110.

267. The bed sheet retention system (or kit) 1000 of any one of embodiments 261 to 266, wherein the system (or kit) 1000 comprises at least one of the herein-described mattress covers 120.

268. The bed sheet retention system (or kit) 1000 of any one of embodiments 261 to 267, wherein the system (or kit) 1000 comprises at least one of the herein-described mattresses 50.

269. The bed sheet retention system (or kit) 1000 of any one of embodiments 261 to 268, wherein the system (or kit) 1000 comprises at least one of the herein-described mattress bands 110'.

270. The bed sheet retention system (or kit) 1000 of any one of embodiments 261 to 269, wherein the system (or kit) 1000 comprises at least one of the herein-described mattress covering strip portions 133.

271. The bed sheet retention system (or kit) 1000 of any one of embodiments 261 to 270, wherein said one or more

of the herein-described sheet locking strips **30** comprises four or more sheet locking strips **30**.

272. The bed sheet retention system (or kit) **1000** of any one of embodiments 261 to 271, further comprising one or more of the herein-described accessories **300**.

273. The bed sheet retention system (or kit) **1000** of any one of embodiments 261 to 272, further comprising one or more inflatable bladders **80**, each inflatable bladder **80** being usable with and/or connectable to one of the herein described brackets **10/40**. See, for example, FIGS. 30A-30C, which disclose exemplary inflatable bladder **80** in combination with exemplary corner bracket **10**.

274. The bed sheet retention system (or kit) **1000** of embodiment 273, wherein said inflatable bladder **80** connects to one of the herein described brackets **10/40**.

275. The bed sheet retention system (or kit) **1000** of embodiment 273 or 274, wherein said inflatable bladder **80** connects to an aperture **20** within a corner bracket **10**.

276. The bed sheet retention system (or kit) **1000** of any one of embodiments 273 to 275, wherein said inflatable bladder **80** comprises a bladder fluid inlet **82** (e.g., an air inlet **82**). It should be noted that bladder fluid inlet **82** can be along any outer surface of said inflatable bladder **80**. In some embodiments, inflatable bladder **80** comprises a bladder fluid inlet **82** along an upper surface **87** of inflatable bladder **80** (as shown in FIG. 30A), and bracket **10/40** (e.g., corner bracket **10**) has an opening **120** therein so that a fluid hose **88** (e.g., an air hose **88**) can be connected to bladder fluid inlet **82**.

277. The bed sheet retention system (or kit) **1000** of any one of embodiments 261 to 276, wherein said inflatable bladder **80** comprises a bladder rim **81** connected to an upper surface **87** of the inflatable bladder **80** via a bladder neck component **85**. The bladder rim **81** and bladder neck component **85** are designed and sized to extend through an aperture **20** within a bracket **10/40** (e.g., corner bracket **10**) so that bladder rim **81** rests along an upper surface of horizontally-extending bracket component **11** surrounding aperture **20**.

278. The bed sheet retention system (or kit) **1000** of any one of embodiments 261 to 277, wherein said inflatable bladder **80** comprises two or more expandable folds **84** that separate from one another when inflatable bladder **80** is inflated. See, for example, uninflated inflatable bladder **80** shown in FIG. 30B, compared to inflated inflatable bladder **80** shown in FIG. 30C. It should be understood that a given inflatable bladder **80** may have any desired number of expandable folds **84** therein.

279. The bed sheet retention system (or kit) **1000** of any one of embodiments 261 to 278, further comprising a fluid hose **88** (e.g., an air hose **88**) that connects a fluid source **90** to a bladder fluid inlet **82** (e.g., an air inlet **82**) of the inflatable bladder **80**.

280. The bed sheet retention system (or kit) **1000** of any one of embodiments 261 to 279, further comprising a fluid source **90** (e.g., an air source) that can be used to inflate the inflatable bladder **80**. The fluid source **90** could be a hand-help pump (not shown) or a foot pump (not shown) or an electric pump (not shown) or any other type of fluid pump.

281. The bed sheet retention system (or kit) **1000** of any one of embodiments 261 to 280, further comprising: (IV) one or more accessories **300**, the one or more accessories **300** comprising the accessory **300** of any one of embodiments 220 to 260.

It should be understood that the bed sheet retention systems (or kits) **1000** of the present invention may comprise one or more additional system/kit components. Suit-

able additional system/kit components include, but are not limited to, one or more bed sheets **70**, one or more sheet connectors (not shown) other than said sheet locking strips **30**, one or more bedmaking tool/mattress-lift tools as described in U.S. patent application Ser. No. 17/983,628, filed on Nov. 9, 2022, and entitled "BEDMAKING TOOLS AND METHODS OF MAKING AND USING THE SAME," the subject matter of which is hereby incorporated by reference in its entirety, one or more bungee cord-type connectors (not shown) that can be used to attached two bed sheet retention devices **100** to one another, diagonally, under a given mattress **50** (i.e., connecting two diagonally opposed bed sheet retention devices **100** to one another via the at least one aperture **20** within each bed sheet retention device **100**), and any combination thereof.

Methods of Making Bed Sheet Retention Devices and Accessories Embodiments

282. A method of making (a) the bed sheet retention device **100/200** of any one of embodiments 1 to 105, or (b) the mattress covering components **110** of embodiments 106 to 188, or (c) the mattress cover **120** of embodiments 189 to 196, or (d) the mattress **50** of embodiments 197 to 207, or (e) the mattress band **110'** of embodiments 208 to 211, or (f) the mattress covering strip portion **133** of embodiments 212 to 219, of (g) the accessories **300** of any one of embodiments 220 to 260, said method comprising: forming the corner bracket **10**, the side bracket **10**, the mattress covering components **110**, the mattress cover **120**, the mattress **50**, the mattress band **110'**, the mattress covering strip portion **133**, and/or the accessory **300** utilizing one or more steps comprising: one or more thermoforming steps (e.g., a molding steps); one or more machining steps (e.g., one or more drilling, cutting, stamping, sanding, abrading, etc., steps); and one or more assembling steps.

283. The method of embodiment 282, wherein said forming step comprises: one or more thermoforming steps (e.g., a molding steps).

284. The method of embodiment 282 or 283, wherein said forming step comprises: a single thermoforming step (e.g., a molding step).

Methods of Using Bed Sheet Retention Devices and Accessories Embodiments

285. A method of using the bed sheet retention device **100/200** of any one of embodiments 1 to 105, said method comprising: inserting the horizontally-extending bracket component **11** between a bottom surface **51** of a mattress **50** and a support surface **60** under the bottom surface **51**; and engaging a sheet material **70** with the one or more sheet-engaging channels **12** of the corner bracket **10**, and/or the side bracket **10**.

286. The method of embodiment 285, wherein said engaging step comprises: engaging a first sheet material portion **71** of a first sheet **70** with the one or more sheet-engaging channels **12** of the corner bracket **10**, and/or the side bracket **10**. See again, FIG. 15.

287. The method of embodiment 285 or 286, wherein said engaging step comprises: engaging two separate sheets **70** (not shown) with the one or more sheet-engaging channels **12** of the corner bracket **10**, and/or the side bracket **10**.

288. The method of any one of embodiments 285 to 287, wherein said engaging step comprises: engaging two sepa-

rate sheets 70 (not shown) with a single sheet-engaging channel 12 of the corner bracket 10, and/or the side bracket 10.

289. The method of any one of embodiments 285 to 287 wherein said engaging step comprises: engaging two separate sheets 70 (not shown) with two or more sheet-engaging channels 12 of the corner bracket 10, and/or the side bracket 10.

290. The method of any one of embodiments 285 to 289, wherein said engaging step comprises: inserting the one or more sheet locking strips 30 recited in any one of embodiments 47 to 54 into the one or more sheet-engaging channels 12 of the corner bracket 10, and/or the side bracket 10.

291. The method of any one of embodiments 285 to 290, wherein said engaging step comprises: independently inserting a single sheet locking strip 30 recited in any one of embodiments 47 to 54 into the one or more sheet-engaging channels 12 of the corner bracket 10, and/or the side bracket 10.

292. The method of any one of embodiments 285 to 291, wherein said method comprises: utilizing the bed sheet retention system (or kit) 1000 of embodiment 142 or 148 to secure one or more sheets 70 to a mattress 50.

293. The method of any one of embodiments 285 to 292, wherein said method further comprises: attaching one or more of the herein-described accessories 300 of any one of embodiments 213 to 253 to the one or more sheet-engaging channels 12 of the corner bracket 10, and/or the side bracket 10 via the at least one accessory connecting member 301 of the one or more of the herein-described accessories 300.

294. The method of embodiment 293, further comprising: adjusting a position of the accessory body 302 of the accessory 300 relative to the one or more sheet-engaging channels 12 of the corner bracket 10, and/or the side bracket 10.

295. The method of embodiment 293 or 294, further comprising: detaching the one or more of the herein-described accessories 300 from the one or more sheet-engaging channels 12 of the corner bracket 10, and/or the side bracket 10.

296. The method of any one of embodiments 285 to 295, wherein said method further comprises: positioning an inflatable bladder 80 under a bracket 10/40 that is positioned so that horizontally-extending bracket component 11 of bracket 10/40 is between a mattress 50 and a support surface 60.

297. The method of any one of embodiments 285 to 296, wherein said method further comprises: connecting an inflatable bladder 80 to a bracket 10/40.

298. The method of any one of embodiments 285 to 297, wherein said method further comprises: connecting an inflatable bladder 80 to aperture 20 of corner bracket 10.

299. The method of embodiment any one of embodiments 296 to 298, wherein said method further comprises: inflating the inflatable bladder 80 to raise bracket 10/40 and the mattress 50 upward in vertical direction D_V.

300. A method of using (a) the mattress covering components 110 of embodiments 106 to 188, or (b) the mattress cover 120 of embodiments 189 to 196, or (c) the mattress 50 of embodiments 197 to 200, or (d) the mattress band 110' of embodiments 201 to 204, or (c) the mattress covering strip portion 133 of embodiments 205 to 212, said method comprising: engaging a sheet material 70 with the one or more sheet-engaging channels 12 of (a) the mattress covering components 110 of embodiments 106 to 188, or (b) the mattress cover 120 of embodiments 189 to 196, or (c) the mattress 50 of embodiments 197 to 200, or (d) the mattress

band 110' of embodiments 201 to 204, or (c) the mattress covering strip portion 133 of embodiments 205 to 212 using one or more locking strips 30.

301. The method of embodiment 300, wherein said method further comprises: attaching one or more of the herein-described accessories 300 of any one of embodiments 213 to 253 to the one or more sheet-engaging channels 12 of (a) the mattress covering components 110 of embodiments 106 to 188, or (b) the mattress cover 120 of embodiments 189 to 196, or (c) the mattress 50 of embodiments 197 to 200, or (d) the mattress band 110' of embodiments 201 to 204, or (c) the mattress covering strip portion 133 of embodiments 205 to 212.

302. The method of embodiment 301, further comprising: adjusting a position of the accessory body 302 of the accessory 300 relative to the one or more sheet-engaging channels 12 of (a) the mattress covering components 110 of embodiments 106 to 188, or (b) the mattress cover 120 of embodiments 189 to 196, or (c) the mattress 50 of embodiments 197 to 200, or (d) the mattress band 110' of embodiments 201 to 204, or (c) the mattress covering strip portion 133 of embodiments 205 to 212.

EXAMPLES

Example 1—Preparation of Corner Brackets

A bed sheet retention system comprised of 4 plastic corner brackets (i.e., 4 bed sheet retention devices such as those shown in FIGS. 1-15 and/or described above in embodiments 9 to 59) was prepared. Each bed sheet retention device featured varying heights of locking tracks/sheet-engaging channels to retain bed sheets. The locking tracks featured a streamlined entry and exit, ensuring that bed sheet material did not get bunched up or hung up when inserting the plastic locking strip.

Each corner bracket/bed sheet retention device was 8.5 inches×8.5 inches×4.3125 inches tall. A hole was in the center of the foot/vertically-extending bracket component of the bracket/bed sheet retention device to reduce the cost of resin required during manufacturing/molding, lighten the product, and improve handling. The clear plastic locking strip was 1-inch-wide×0.0625-inch-thick×15.5 inches long. It had 1/2 inch radius on the corners making the ends round and the edges were radiused at maximum of 0.03125 inches to give the plastic striping a very smooth finish without corners or edges. This locking strip slid into 1 of the 1 to 3 (or more if available) retention track selections offered (i.e., sheet-engaging channels offered). These tracks profiles were 1.1875 inches tall×0.1875 inches wide, with radius in the corners. These dimensions provided necessary tolerance for the locking strip to easily slide into the track with a bed sheet trapped in its path. This tolerance also allowed for a secondary locking strip to be inserted, trapping the flat bed sheet as well as another 0.0625 thick locking strip. This optional second strip was to lock into place the flat sheet of the bed at the foot of the bed.

The locking channels interior was radius, providing a smooth journey for the locking strip to run through. The inside lip of the flange was kept at a sharper radius to improve the material wrap and maintain a strong angle for allowing the material to draw the locking strip up into the top of the channel. This edge along with the tolerances was what provided an excellent locking mechanism for the strips and sheeting material. This also allowed for very easy installation of these locking strips.

The corner bracket was designed so that there were up to three channels, which allowed the locking strips to follow. Each sheet-locking channel had a landing, an entry, a locking flange, an exit, a guided corner bend, and then on the perpendicular side at 90 degrees around the corner of the bracket, another landing, entry, locking flange, and exit. This was so that the locking strip can lock the sheet on 2 sides of the corner utilizing a single locking strip.

Each sheet-locking channel was broken up into 3 separate sections: (a) two sheet-locking flanged sides/channels, and (b) an unflanged, open guided channel around the corner of the bracket/bed sheet retention device. The landing on the entry of the corner bracket/bed sheet retention device were 1.0 inch deep to allow for a good seating of the locking strip to stage the entry of collected bed sheet material. The inside of the corner bracket/bed sheet retention device was smooth and had a reinforced radius in the bottom connecting to the bracket's/bed sheet retention device's vertically-extending walls.

The foot pad/horizontally-extending bracket component of the corner bracket/bed sheet retention device was positioned under a mattress and pinned in place. This foot pad/horizontally-extending bracket comprised a large hole as previously described, but its edges were chamfered and tapered to a sharp edge. This edge allowed for the foot/horizontally-extending bracket of the bracket/bed sheet retention device to easily penetrate and slide between the mattress and the foundation the bed sits on. This edge was continuous around the foot of the bracket/bed sheet retention device, allowing for the corner bracket to be inserted from either direction. The large 5.5-inch hole in the center of the foot pad/horizontally-extending bracket component of the corner bracket/bed sheet retention device was radiused to a complete semi-circle which prevented sharp edges and improved handling when holding the bracket/bed sheet retention device. The inside corner wall of the bracket/bed sheet retention device had a radius which matches most industry standard mattresses at 2.5 inches radius. All edges of the bracket/bed sheet retention device were radiused so that there were no sharp edges to damage the sheeting materials. Alternatives to the above-described bracket/bed sheet retention device were also prepared, including brackets/bed sheet retention devices comprised of male tracks with female type clips, narrow track vents with flat stripping that can hem the sides down, tapered wedges, buttons, snaps, crimps, or the like. All brackets/bed sheet retention devices were simple to use, and could be made in various colors and plastics.

The above-described brackets/bed sheet retention device were produced initially out of a glass-filled polyolefin to insure rigidity. Then, the above-described brackets/bed sheet retention device were produced of either a single solid molded plastic or a multi-part assembled plastic assembly. Cheaper plastics like ABS and the like were used.

The clear locking strip was made from acrylic or polycarbonate. Acrylic was the preferred material for forming clear locking strips given that it was more economical and had great visibility and clarity with great flexibility and rigidity. These locking strips were made with and without a hole at opposite ends and/or a gripping device for the thumb or fingers of a user.

Example 2—Preparation of Side Brackets

Side brackets **40**, such as those shown in FIGS. 16-24 and described above in embodiments 60 to 105, were prepared using procedures and materials similar to those described in

Example 1. The resulting side brackets **40** were used to secure sheet **70** along the side of a mattress **50**.

Example 3—Preparation of Accessories

Accessories **300**, such as those shown in FIGS. 25A-29B and described above in embodiments 220 to 260, were prepared using procedures and materials similar to those described in Example 1. The resulting accessories **300** were used by attaching a given accessory **300** to the corner brackets **10** formed in Example 1 and/or the side brackets **40** formed in Example 2 so as to position at least a portion of the accessory **300** (i) above the one or more sheet-engaging channels **12**, and/or (ii) below the one or more sheet-engaging channels **12**, and/or (iii) within a horizontal plane **P** containing the one or more sheet-engaging channels **12** of the corner bracket **10** or side bracket **40**.

Example 4—Use of Inflatable Bladders

Inflatable bladders **80**, such as those shown in FIGS. 30A-30C and described above in embodiments 273 to 280, were prepared using conventional procedures and materials (e.g., rubber/elastic material). Four resulting inflatable bladders **80** were used by (a) attaching a given inflatable bladder **80** to an aperture **20** of one of four corner brackets **10** formed in Example 1, and (b) positioning the four inflatable bladders **80**/corner brackets **10** combination at the corners of a mattress **50**. The four resulting inflatable bladders **80** were independently inflated to alter upward/downward a given corner of the mattress **50**.

Example 5—Preparation of Mattress Covers, Mattresses, Mattress Bands, and Mattress Covering Strip Portions

Mattress covering components **110** as described in embodiments 106 to 188, mattress covers **120** as described in embodiments 189 to 196, mattresses **50** as described in embodiments 197 to 207, mattress bands **110'** as described in embodiments 208 to 211, and mattress covering strip portions **133** as described in embodiments 212 to 219, and as shown in FIGS. 32-41, were prepared using conventional processing steps (e.g., molding, attaching, etc.). The bed sheet retention products **110/120/50/110'/133/133'** were used to hold bed sheets **70** onto a mattress **50**. The bed sheet retention products **110/120/50/110'/133/133'** were also used in combination with accessories **300** prepared in Example 3 and described in embodiments 220 to 260.

It should be understood that although the above-described bed sheet retention devices, attachable accessories, bed sheet retention systems, and/or methods are described as "comprising" one or more components or steps, the above-described bed sheet retention devices, attachable accessories, bed sheet retention systems, and/or methods may "comprise," "consists of," or "consist essentially of" any of the above-described components, features, or steps of the bed sheet retention devices, attachable accessories, bed sheet retention systems, and/or methods. Consequently, where the present invention, or a portion thereof, has been described with an open-ended term such as "comprising," it should be readily understood that (unless otherwise stated) the description of the present invention, or the portion thereof, should also be interpreted to describe the present invention, or a portion thereof, using the terms "consisting essentially of" or "consisting of" or variations thereof as discussed below.

As used herein, the terms "comprises," "comprising," "includes," "including," "has," "having," "contains," "containing," "characterized by" or any other variation thereof, are intended to encompass a non-exclusive inclusion, subject to any limitation explicitly indicated otherwise, of the recited components. For example, a bed sheet retention device, an attachable accessory, bed sheet retention system, and/or method that "comprises" a list of elements (e.g., components, features, or steps) is not necessarily limited to only those elements (or components or steps), but may include other elements (or components or steps) not expressly listed or inherent to the bed sheet retention device, the accessory, bed sheet retention system, and/or method. 10

As used herein, the transitional phrases "consists of" and "consisting of" exclude any element, step, or component not specified. For example, "consists of" or "consisting of" used in a claim would limit the claim to the components, materials or steps specifically recited in the claim except for impurities ordinarily associated therewith (i.e., impurities within a given component). When the phrase "consists of" or 15 "consisting of" appears in a clause of the body of a claim, rather than immediately following the preamble, the phrase "consists of" or "consisting of" limits only the elements (or components or steps) set forth in that clause; other elements (or components) are not excluded from the claim as a whole. 20

As used herein, the transitional phrases "consists essentially of" and "consisting essentially of" are used to define a bed sheet retention device, an accessory, bed sheet retention system, and/or method that includes materials, steps, features, components, or elements, in addition to those literally disclosed, provided that these additional materials, steps, features, components, or elements do not materially affect the basic and novel characteristic(s) of the claimed invention. The term "consisting essentially of" occupies a 30 middle ground between "comprising" and "consisting of."

Further, it should be understood that the herein-described bed sheet retention devices, attachable accessories, bed sheet retention systems, and/or methods may comprise, consist essentially of, or consist of any of the herein-described components and features, as shown in the figures with or 40 without any feature(s) not shown in the figures. In other words, in some embodiments, the bed sheet retention devices, attachable accessories, bed sheet retention systems, and/or methods of the present invention do not have any additional features other than those shown in the figures, and 45 such additional features, not shown in the figures, are specifically excluded from the bed sheet retention devices, attachable accessories, bed sheet retention systems, and/or methods. In other embodiments, the bed sheet retention devices, bed sheet retention systems, and/or methods of the 50 present invention do have one or more additional features that are not shown in the figures.

While the specification has been described in detail with respect to specific embodiments thereof, it will be appreciated that those skilled in the art, upon attaining an understanding of the foregoing, may readily conceive of alterations to, variations of, and equivalents to these embodiments. Accordingly, the scope of the present invention should be assessed as that of the appended claims and any equivalents thereto.

What is claimed is:

1. A bed sheet retention system for securing one or more bed sheets to a bed, said bed sheet retention system comprising:

(I) one or more brackets, each of the brackets comprising
(A) a horizontally-extending bracket component sized and designed to extend between a bottom surface of a

mattress and a support surface under the bottom surface, and (B) one or more sheet-engaging channels positioned along one or more side surfaces of the bracket, each of the sheet-engaging channels comprising a sheet-locking member comprising (i) an upper sheet-locking channel member, and (ii) a lower sheet-locking channel member positioned below and spaced from said upper sheet-locking channel member, wherein each of said upper sheet-locking channel member and said lower sheet-locking channel member (a) are designed to engage with one or more sheet locking strips inserted within the sheet-locking member from the upper sheet-locking channel member to the lower sheet-locking channel member, and (b) together provide a channel track profile that extends along a length of the sheet-locking member, wherein said channel track profile (A) has a channel cross-sectional shape along the length of the sheet-locking member, said channel cross-sectional shape being a cross-sectional rectangular shape, and (B) a track profile height H_{TP} that is at least two times greater than a track profile width W_{TP} of the channel track profile; wherein each of the sheet-engaging channels of said one or more sheet-engaging channels comprises (1) an upper channel side wall extending away from said bracket, and forming a portion of said upper sheet-locking channel member, (2) a lower channel side wall extending away from said bracket, and forming a portion of said lower sheet-locking channel member, (3) an upper strip engaging member extending downward from said upper channel side wall and towards said lower sheet-locking channel member, and (4) a lower strip engaging member extending upward from said lower channel side wall and towards said upper sheet-locking channel member, wherein the one or more brackets are separate from and combinable with the mattress so as to cover at least a portion of one or more side surfaces of the mattress; and

(II) the one or more sheet locking strips, (A) each of the sheet locking strips being sized and designed to (a) be inserted within the channel track profile of the sheet-locking member from (i) said upper sheet-locking channel member to (ii) said lower sheet-locking channel member, and (b) lock the one or more bed sheets within the sheet-locking member so that (i) an upper portion of the one or more bed sheets extends above the sheet-locking member and towards an upper surface of the mattress, and (ii) a lower portion of the one or more bed sheets extends below the sheet-locking member and towards the bottom surface of the mattress, and (B) each of the sheet locking strips having a strip cross-sectional rectangular shape.

2. The bed sheet retention system of claim 1, wherein the channel track profile has the channel cross-sectional shape in 55 which the track profile height H_{TP} is from two times greater to about eight times greater than the track profile width W_{TP} of the channel track profile.

3. The bed sheet retention system of claim 1, wherein the channel cross-sectional shape is symmetrical along opposite 60 sides of a channel dissecting line L_D extending vertically through the channel track profile.

4. The bed sheet retention system of claim 1, wherein the channel track profile is bound by (i) an inner surface of said upper channel side wall, (ii) an inner surface of said lower channel side wall, (iii) an inner surface of said upper strip engaging member, (iv) an inner surface portion of a gap between said upper strip engaging member and said lower

strip engaging member, (v) an inner surface of said lower strip engaging member, and (vi) an inner surface opposite said gap.

5. The bed sheet retention system of claim 1, wherein said one or more brackets comprise one or more corner brackets, and each of said one or more corner brackets comprises (i) a first sheet-locking member extending along one of the side surfaces of the mattress, and (ii) a second sheet-locking member extending along an adjacent side surface of the mattress so that the first sheet-locking member and the second sheet-locking member are normal to one another. 10

6. The bed sheet retention system of claim 5, wherein said one or more sheet-engaging channels are connected to said horizontally-extending bracket component via one or more bracket side walls extending from said horizontally-extending bracket component to an upper rim of said corner bracket, wherein each of the sheet-engaging channel channels (1) comprises the sheet-locking member extending along an outer surface of the corner bracket, and (2) extends substantially within a plane P parallel with said horizontally-extending bracket component or at an angle A to the plane P parallel with said horizontally-extending bracket component. 15

7. The bed sheet retention system of claim 1, wherein said one or more brackets comprise one or more side brackets, and each of said one or more side brackets comprises at least one of the sheet-locking member extending along one of the side surfaces of the mattress. 20

8. The bed sheet retention system of claim 7, wherein said one or more sheet-engaging channels are connected to said horizontally-extending bracket component via one or more bracket side walls extending from said horizontally-extending bracket component to an upper rim of said side bracket, wherein each of the sheet-engaging channels (1) comprises the sheet-locking member extending along an outer surface of the side bracket, and (2) extends (i) substantially within a plane P parallel with said horizontally-extending bracket component or at an angle A to the plane P parallel with said horizontally-extending bracket component. 30

9. The bed sheet retention system of claim 1, wherein said one or more sheet locking strips comprises four or more sheet locking strips, and each of the sheet locking strips has a strip width W_s of from about 0.5 in to about 1.5 in, a strip thickness T_s of from about 0.05 in to about 0.10 in, and a strip length L_s of from about 4.0 in to about 18.0 in. 40

10. The bed sheet retention system of claim 1, wherein said one or more brackets comprise (i) one or more corner brackets, (ii) one or more side brackets, or (iii) both (i) and (ii). 50

11. The bed sheet retention system of claim 1, wherein each of the brackets further comprises one or more bracket side walls extending from said horizontally-extending bracket component to an upper rim of said bracket, and each of the one or more sheet-engaging channels is positioned along said one or more bracket side walls. 55

12. The bed sheet retention system of claim 1, wherein each of said one or more sheet-engaging channels comprises the channel track profile having (i) a track profile length L_{TP} of from about 2.5 inches (in) to about 67.5 in, (ii) the track profile height H_{TP} of from about 0.3 in to about 3.0 in, and (iii) the track profile width W_{TP} of from about 0.1 in to about 1.5 in. 60

13. A bed sheet retention system for securing one or more bed sheets to a bed, said bed sheet retention system comprising:

- (I) one or more brackets, each of the brackets comprising
  - (A) a horizontally-extending bracket component sized

and designed to extend between a bottom surface of a mattress and a support surface under the bottom surface, (B) one or more bracket side walls extending from said horizontally-extending bracket component to an upper rim of said bracket, and (C) one or more sheet-engaging channels positioned along one or more side surfaces of the one or more bracket side walls, each of the sheet-engaging channels comprising a sheet-locking member comprising (i) an upper sheet-locking channel member, and (ii) a lower sheet-locking channel member positioned below and spaced from said upper sheet-locking channel member, wherein each of said upper sheet-locking channel member and said lower sheet-locking channel member (a) are designed to engage with one or more sheet locking strips inserted within the sheet-locking member from the upper sheet-locking channel member to the lower sheet-locking channel member, and (b) together provide a channel track profile that extends along a length of the sheet-locking member, wherein said channel track profile has (A) a channel cross-sectional shape along the length of the sheet-locking member, said channel cross-sectional shape being a cross-sectional rectangular shape, and (B) a track profile height H_{TP} that is at least two times greater than a track profile width W_{TP} of the channel track profile; wherein each of the sheet-engaging channels of said one or more sheet-engaging channels comprises (1) an upper channel side wall extending away from said bracket, and forming a portion of said upper sheet-locking channel member, (2) a lower channel side wall extending away from said bracket, and forming a portion of said lower sheet-locking channel member, (3) an upper strip engaging member extending downward from said upper channel side wall and towards said lower sheet-locking channel member, and (4) a lower strip engaging member extending upward from said lower channel side wall and towards said upper sheet-locking channel member,

wherein the one or more brackets are separate from and combinable with the mattress so as to cover at least a portion of one or more side surfaces of the mattress; and

(II) the one or more sheet locking strips, (A) each of the sheet locking strips being sized and designed to (a) engage with said one or more sheet-engaging channels and extend from (i) said upper sheet-locking channel member to (ii) said lower sheet-locking channel member, and (b) lock the one or more bed sheets within the sheet-locking member so that (i) an upper portion of the one or more bed sheets extends above the sheet-locking member and towards an upper surface of the mattress, and (ii) a lower portion of the one or more bed sheets extends below the sheet-locking member and towards the bottom surface of the mattress, and (B) each of the sheet locking strips having a strip cross-sectional rectangular shape.

14. The bed sheet retention system of claim 13, wherein said one or more brackets comprise (i) one or more corner brackets, (ii) one or more side brackets, or (iii) both (i) and (ii). 65

15. The bed sheet retention system of claim 13, wherein each of said one or more sheet-engaging channels comprises the channel track profile having (i) a track profile length L_{TP} of from about 2.5 inches (in) to about 67.5 in, (ii) the track profile height H_{TP} of from about 0.3 in to about 3.0 in, and (iii) the track profile width W_{TP} of from about 0.1 in to about 1.5 in.

59

16. A bed sheet retention system for securing one or more bed sheets to a bed, said bed sheet retention system comprising:

- (I) one or more brackets, each of the brackets comprising
  - (A) a horizontally-extending bracket component sized and designed to extend between a bottom surface of a mattress and a support surface under the bottom surface, (B) one or more bracket side walls extending from said horizontally-extending bracket component to an upper rim of said bracket, and (C) one or more sheet-engaging bracket components positioned along one or more side surfaces of the bracket; and
- (II) one or more sheet locking components, each of the sheet locking components having a cross-sectional rectangular shape being sized and designed to engage with the one or more sheet-engaging bracket components so as to secure the one or more bed sheets (1) between (i) the one or more sheet-engaging bracket components, and (ii) the one or more sheet locking components so that (a) an upper portion of the one or more bed sheets extends above the one or more sheet-

engaging bracket components and towards an upper surface of the mattress, and (b) a lower portion of the one or more bed sheets extends below the one or more sheet-engaging bracket components and towards the bottom surface of the mattress, and (2) within a channel track profile of the one or more sheet-engaging bracket components, the channel track profile having (A) a cross-sectional rectangular shape, and (B) a track profile height H_{TP} that is at least two times greater than a track profile width W_{TP} of the channel track profile.

17. The bed sheet retention system of claim **16**, wherein the channel track profile has (i) a track profile length L_{TP} of from about 2.5 inches (in) to about 67.5 in, and (ii) the track profile height H_{TP} is from about 0.3 in to about 3.0 in, and (iii) the track profile width W_{TP} is from about 0.1 in to about 1.5 in.

18. The bed sheet retention system of claim **17**, wherein the channel track profile has a cross-sectional rectangular shape.
